UNITED STATES PATENT OFFICE.

JOHN ERICKSON, OF CHICAGO, ILLINOIS, ASSIGNOR, BY MESNE ASSIGNMENTS, TO
AUTOMATIC ELECTRIC INC., OF CHICAGO, ILLINOIS, A CORPORATION OF DELAWARE.

AUTOMATIC TELEPHONE SYSTEM.

Application filed March 13, 1905. Serial No. 249,709.

To all whom it may concern:

Be it known that I, JOHN ERICKSON, a citizen of the United States of America, and resident of Chicago, Cook County, Illinois, 5 have invented a certain new and useful Improvement in Automatic Telephone Systems, of which the following is a specification.

My invention relates to automatic telephone systems in general, but more particularly to systems of that character in which any subscriber may, through the medium of suitable selective apparatus, establish connection with the line of any other subscriber of the system, providing, of course, that such 15 line is not busy, and especially to automatic telephone systems in which the mechanism or apparatus by which one subscriber makes connection with another subscriber's line, without the aid of a telephone operator or 20 other attendant, consists of a suitable number of switches which operate on the step-by-step principle and which are, by reason of the provision of suitable switching apparatus at the subscribers' stations, under the 25 control of, and adapted to be operated by, the different subscribers.

Prior to my invention, it has been the general practice, so far as I am aware, to employ, in a telephone system of the above 30 particular character, either a number of switches corresponding in number to the total number of subscribers, each of said switches being allotted and individual to a single subscriber, and each switch thus being 35 used only by the subscriber to whom it is allotted in establishing connection, either directly or indirectly, with the line of some other subscriber, or one or more constantly operating switches for picking up calls. 40 These individual switches, if adapted to receive the impulse or impulses corresponding to the first digit of the called number, are known as first "selectors", provided, of course, that the exchange is of such size as 45 to necessitate the use of a plurality of switches in establishing connection between two subscribers' lines. Again, it has been proposed to reduce the number of said first "selectors" to a percentage basis that is to 50 say, to employ, for example, only ten or twenty so-called first "selectors" for each one hundred subscribers in the exchange, each group of "selectors" thereby being common to a larger number of subscribers; and 55 with an arrangement of this character it has

been the practice to then provide each subscriber with a so-called "individual-switch" adapted to be operated by one or more impulses projected by the subscriber over the line preliminary to calling the number of 60 the desired subscriber. Other more or less similar constructions and arrangements have been proposed, the object being generally to reduce the number of switches in the exchange as much as possible; but in each 65 case, so far as I am aware, it has always been necessary, prior to my invention either to employ constantly operating switches, or to provide each subscriber with an individual 70 selective switching device of some character—that is to say, the number of step-by-step or other suitable selective switching devices, through the medium of which any subscriber makes the initial connection necessary in establishing connection with any 75 other subscriber's line, always corresponding to the total number of subscribers' stations having connection with the exchange or central station. In other words, and regardless of the arrangement and division 80 of the switching devices, it has always been necessary, prior to my invention, either to employ constantly operating switches, or to provide each telephone subscriber with some 85 sort of a selective switching device, that is, a trunk-selecting or line-connecting device individual to his line. For example, in my prior application, Serial No. 249,499, filed by me on the tenth day of March, 1905, for improvements in automatic electrical switching means, there is a switch-operating machine common to all of the members of a group of subscribers, each subscriber, however, being provided with an "individual-switch"—that is to say, a step-by-step switching device which is allotted to a subscriber's line and used only by that subscriber, although all of the different "individual-switches" are operated through the medium 90 of a switch-operating machine which is common to all of the subscribers in the group; but in the present case, as will hereinafter more fully appear, one of the principal objects to be attained is the reduction of all 95 step-by-step switches to a percentage basis, so as to materially reduce the amount of switching machinery and apparatus necessary for service between the subscribers, and whereby practically none of the devices in 100 the central station or exchange are individ- 105 110

ual to the subscribers' lines except, perhaps, in the matter of "line-relays" or other similar extremely simple controlling devices, as will hereinafter more fully appear; and the 5 dispensing with all constantly operating switches or circuit-controlling machinery.

Generally stated, therefore, the object of my invention is to provide such an improved construction and arrangement as will afford 10 satisfactory and efficient telephone service between the different subscribers, but without the necessity of providing each subscriber with an individual selective switching device, and with the further advantage of a 15 material reduction in the amount of apparatus or selective switching devices necessarily employed at the exchange or central station.

A special object is to provide an improved 20 construction and arrangement involving a selective switching apparatus which may be used in common by a group of subscribers of any suitable number, and which, after serving the purpose of one subscriber in making 25 the first connection necessary in establishing connection with some other subscriber's line, will then automatically place itself in such condition as to be in readiness for use by the next subscriber of the group desiring to call 30 some other subscriber, the time required by the said apparatus in establishing the desired connection being of such short duration that it can, even though the different subscribers 35 of the group send in calls in rapid succession, always attend to the wants of each subscriber, it being extremely unlikely that any two subscribers will simultaneously take 40 down their receivers and attempt to use the said apparatus at the same time.

Another object is to provide an improved 45 construction and arrangement whereby a selective switching apparatus may be used in common by a number of subscribers as the means for making the first connection necessary in establishing connection with the called subscriber, and in combination with a group of first "selectors" considerably less in number than the group of subscribers to whom the apparatus as a whole is allotted, 50 it being possible with this arrangement to employ, for example, only ten first "selectors" for each one hundred subscribers, the said selective switching apparatus which is common to the one hundred subscribers being adapted to switch a calling subscriber's line to any one of the said ten first "selectors", the "selector" thus picked out being, 55 of course, one that is not then in use by another subscriber of the same group.

A further object is to provide an improved 60 normally at rest trunk-selecting and connecting apparatus interposed between the subscribers' lines and the first-selectors or other suitable means for making connections in accordance with the called number.

It is also an object, of course, to provide certain details and features of construction tending to increase the general efficiency, economy of installation and maintenance, and serviceability of an automatic telephone 70 system of this particular character.

In many respects, my present invention constitutes a matter of improvement over or upon the telephone system and devices disclosed in my said prior application. For 75 example, in my said prior application I show an arrangement by which a single switch operating machine may be made common to all of the members of a group of subscribers, and by which this machine may be employed 80 by any subscriber in such group as a means for operating one of a number of step-by-step switches, so as to connect the calling subscriber's line with a trunk-line, and without interfering with the subsequent and 85 practically immediate use of the said machine by other subscribers for establishing other connections while the operated switch remains in use; but with the arrangement 90 hereinafter described and claimed, the switches which are operated automatically by the switch-operating machine, instead of being each individual to a subscriber, are considerably less in number than the total 95 number of subscribers and are, furthermore, electrically connected with the said switch-operating machine, instead of being connected mechanically therewith, as in my said prior application. Consequently, as previously stated, one advantage of my present 100 invention resides in the fact that practically none of the devices in the exchange are individual to the different subscribers, each step-by-step switch, or other switching device capable of making any one of a number 105 of possible connections, being common to a plurality of subscribers, and nothing except the number of "line-relays", or other similar simple devices, being the same in 110 number as the total number of subscribers.

In the accompanying drawings, Fig. 1 is a diagrammatic view illustrating the electrical construction and circuit arrangement of the said selective switching device which is common to the said group of one hundred subscribers, more or less.

Fig. 2 is a diagrammatic view illustrating the electrical construction and circuit arrangement of one of the "preliminary-connectors" which are arranged in groups of ten, more or less, and each group being allotted to a group of one hundred subscribers, more or less.

Fig. 3 is a plan view of the machine or switching apparatus illustrated diagrammatically in Fig. 1, and showing also several of the "line" or "individual" relays.

Fig. 4 is an end elevation of the selective switching device shown in Fig. 3.

Fig. 5 is a section on line 5—5 in Fig. 3,

looking in the direction indicated by the arrows.

Fig. 6 is a detail showing a different position of some of the parts shown in Fig. 5.

Fig. 7 is a detail section on line 7-7 in Fig. 4.

Fig. 8 is a horizontal section on line 5-5 in Fig. 3, but looking in a direction opposite to that indicated by the arrows.

Fig. 9 is another end elevation of the selective switching device shown in Fig. 3.

Fig. 10 is a detail section on line 10-10 in Fig. 8.

Fig. 11 is a detail perspective of one of the spring-switch devices involved in the construction of the said selective switching device.

Fig. 12 is a diagrammatic representation of a subscriber's telephone and switching outfit.

Fig. 13 illustrates the mechanical construction of one of the "preliminary-connectors" which constitute a new feature in an automatic telephone system.

Fig. 14 illustrates an ordinary "connector-switch", the same being adapted for use in making the final connection with the called subscriber's line, and which is herein shown, described and claimed in combination with other features, but which in itself is not new.

Fig. 15 is a diagram illustrating the circuit connections existing during the time two subscribers' lines are connected up for conversation in a system in which it is assumed that only a comparatively small number of subscribers are involved, and in which no first, second or third "selectors" are employed, an ordinary "connector" being sufficient for the requirements of the calling subscriber after the preliminary connections have been made.

Fig. 16 is an enlarged detail view of one of the series of relays shown in Fig. 1.

Fig. 17 is a diagram showing the capacity of the system increased, say from a one hundred to a one thousand system. In this figure the trunk conductors L-L leading from the wipers of the "preliminary-connector" or non-numerical "selector" terminate in a "selector-switch" N, instead of in a "connector" as in Fig. 15. The "selector" N is of the general type described in United States Patent No. 815,321, granted March

13, 1906, to Keith, Erickson & Erickson. From each set of bank-contacts of this "selector" a trunk line leads off, which terminates in a "connector-switch" such as the one shown in Fig. 15. One of these

trunk lines is shown comprising the conductors L¹ and L². In other words, the "selector" N is properly inserted (in Fig. 15) between the trunk-connecting switch and the "connector".

Fig. 18 shows diagrammatically a second

"selector" which, if the system is still further increased in capacity, as from one-thousand to ten-thousand, is inserted between the first "selector" N and the "connector-switch".

Fig. 19 shows diagrammatically a third "selector-switch" which is used when the central office is arranged for a one-hundred-thousand system. The "selector" O is shown connected with the "connector-switch" M, which is the same as the "connector" shown in Fig. 15.

As thus illustrated, and with a view to a more general understanding of the construction and operation of my improved automatic telephone system, before going into a more thorough description of the details of the construction, the arrangement and mode of operation are as follows: The subscribers may be divided into groups of one hundred each. Each subscriber may be provided with any suitable kind of apparatus, such, for example, as shown in Fig. 12. Each subscriber's line terminates at the exchange or central station in a "line-relay", such, for example, as the "line-relay" shown at the right in Fig. 2. At the central station each line is also preferably normally connected with the bank-contacts of a suitable number of automatic switches, say ten, of the step-by-step switches shown at the left in Fig. 2. In addition, an automatic switching device of the character shown in Fig. 1 is allotted to each group of subscribers and associated with the ten step-by-step switches shown in Fig. 2. When

the subscriber starts to call another subscriber, the act of removing the receiver operates the "line-relay" at which the line of the calling subscriber terminates. This, of course, precedes the operation of calling the number of the desired subscriber, and all occurs in the interval between the removal of the calling subscriber's receiver and the transmission of the first impulse or impulses necessary to calling the desired number. As soon as the "line-relay" operates, it throws the apparatus shown in Fig. 1 into operation, and from then on until the subscriber begins calling the desired number, the operation is strictly automatic. As soon as the automatic switching device shown in Fig. 1 is started by any one of the subscribers in the group to which this switch is allotted, it automatically picks out an idle member of the group of ten step-by-step switches—that is to say, the ten step-by-step switches of the character shown in Fig. 2, and which are allotted to the aforesaid group of one hundred subscribers, and to the switching apparatus shown in Fig. 1. The arrangement is also such that the switch shown in Fig. 1 is preferably always connected up with one of the switches shown in Fig. 2—that is to say, with one of the ten switches which is not busy. Consequently, the ap-

100

105

110

115

120

125

130

paratus shown in Fig. 1, as soon as set in motion, automatically calls the number of the calling subscriber. In other words, the switch shown in Fig. 1 automatically transmits impulses corresponding to the number of the calling subscriber, causing the switch in Fig. 2 to select the bank-contacts connected with the calling subscriber's line. In this way, the calling subscriber, by simply 5 removing the receiver, or in any other suitable way, automatically calls his own line, so to speak, and thereby establishes connection with an idle trunk-line running to a so-called first "selector", for example, or 10 to some other switch. As soon as this has been done, the subscriber is then, and by that time, ready to begin the operation of calling the desired number: but he is only connected with the said first "selector", or other switch, 15 from the time he begins making the call until the conversation is terminated and the switches restored to their normal positions. Thus there are no "individual-switches", the "line-relays" being practically the only 20 devices which are each made individual to a single subscriber. Obviously, therefore, the number of so-called first "selectors", and other necessary switches, may be considerably less in number than the total number 25 of subscribers, and with the result that the apparatus is simplified and materially reduced without in any way reducing the efficiency of service between subscribers. This, of course, is largely due to the fact 30 that the automatic switch shown in Fig. 1, after automatically calling the number of the calling subscriber, and thereby establishing connection between the calling subscriber's line and one of the ten switches 35 shown in Fig. 2, then returns to its normal condition and remains in readiness for use by another subscriber of the same group. With this arrangement, therefore, the switch 40 shown in Fig. 1 is, unless two subscribers 45 of the group to which it is allotted simultaneously take down their receivers, etc., which is extremely unlikely, always in readiness to be employed by any subscriber of the group for the purpose of connecting 50 his line with an idle first "selector". Thus, notwithstanding the fact that there are no step-by-step selective switches which are individual to the subscribers, the operation, as far as the calling subscriber is concerned, is 55 practically the same as if each line terminated in a so-called first "selector" or other similar switch. In other words, the calling subscriber, by simply removing his receiver from the usual switch-hook, automatically 60 starts a train of electrical steps or operations which are completed by the time he is ready to begin calling the desired number: and, without any hesitation or additional work 65 on the part of the calling subscriber, a first "selector", a "connector", or other switch,

according to the size of the exchange, is thus placed in electrical communication with his line and in readiness to receive the impulse or impulses corresponding to one or more digits of the called number, as the case may 70 be. From this point on, the apparatus and the operation may be of any suitable, known or approved character, my invention relating more particularly to that part of the operation which is included between the 75 time of taking down the calling subscriber's receiver and the consequent automatic connection with an idle first "selector", or other switch; and the devices then used for calling the desired number, and for completing the 80 connection through to the called subscriber's line, may be of any suitable, known or approved character.

In a general way, and before describing the details of construction, the operation of 85 connecting up one subscriber's line with another is as follows: Suppose, for example, that the subscriber at station A (Fig. 15), and whose number may be assumed is 51, desires to converse with the subscriber at 90 station B, it being assumed that the latter's number is 99, and also that, as a matter of convenience of illustration, the two subscribers belong to the same group to which the previously mentioned switch-operating 95 machine is allotted; although, of course, it will be understood that the exchange may be of any suitable or desirable size, the only difference, in a general way, between one of one hundred subscribers and one of, say, ten 100 thousand subscribers being with respect to the number of automatic switches which any given subscriber must employ in connecting his line with the line of some other subscriber. With the arrangement shown, however, subscriber 51, in removing his receiver from the switch-hook a , will thereby produce a momentary engagement of the switch-hook projection a^1 with the switch-constant a^2 (Fig. 12). This, it will be seen, 105 momentarily grounds the subscriber's line-conductor l , the grounded circuit thus momentarily formed including this line-conductor, the conductors a^3 , a^4 , the said switch-hook, the contact a^2 , the conductor a^5 , the contacts a^6 , a^7 , to ground at a^8 . In this 110 way, the removal of the receiver momentarily grounds one side of the calling subscriber's line, with the result that the relay-coil 7 (Fig. 15), which is one of the two 115 relay-coils 6 and 7—normally bridged across the subscriber's line, and normally connected at the middle point with contacts 8, 9 and 10, the latter being connected with a non-grounded pole of battery 11—is energized sufficiently to attract the armature 12. In other words, the momentary grounding of the subscriber's line completes a temporary grounded circuit including the coil 7, and including the battery 11. When 120

thus energized, the subscriber's "line-relay", by attracting its armature 12, causes the normally-separated contacts 3, 4 and 5 to be brought into engagement with each other, 5 it being seen that contact 5 is connected to ground (Fig. 1). This, it will be seen, completes a circuit from ground through contact 3 of conductor 17 to relay-coil 15, thence over conductor 19, contact-arm 24, contact-arm 21, relay-coil 25, conductor 26 to the non-grounded pole of battery 11, and thence to ground again. In this way, the energizing 10 of the subscriber's "line-relay" is instantly followed by the energizing of the inner relay-coil 15, causing this relay to attract its armature, and by the energizing of relay 25, which latter also attracts its armature. Simultaneously with the formation of these circuits and the energizing of 15 these relays, however, another circuit is closed from ground through contact-arm 4 to conductor 18, thence over inner relay-coil 16, over conductor 19, through contact-arms 24 and 21, through relay-coil 25, and over conductor 26 to battery 11 and thence to ground. Obviously, with the arrangement 20 shown, the inner relay-coil 16 when energized will cause its armature 14 to break contact with the contact-point 27, and the inner relay-coil 15, when energized as described, attracts its armature 13, thereby causing the latter to break contact with the contact-point 28. At the same time, the energizing of relay-coil 25 will cause its 25 armature to engage the contact-point 30, thus closing a circuit as follows: From battery 11 through conductor 26, through contacts 30 and 29, through "rotary-magnet-coil" 31, thence through normally-engaging 30 circuit-breaking contacts 33 and 32 to ground and back to battery. This "rotary-magnet", when thus energized, attracts its armature 13^b, causing the latter to separate the contacts 32 and 33, and thereby permitting the armature to be instantly released. As will hereinafter more fully appear, the construction of the said "rotary-magnet" is such that each time its armature 35 is released it causes its pawl to engage a tooth of the ratchet-wheel on the switch-shaft, to which latter is attached a spring-wiper or contact-brush 35, the latter resting normally on a series of contact-teeth or switch-contacts arranged in a circle. Consequently, and as the armature 13^b is alternately attracted and released, owing to the rapid make-and-break action which it produces in the coil 31, the spring-wiper 35 is given a rapid step-by-step motion over the said contact-teeth or switch-contacts. The spring-wiper 35 is, as shown in Fig. 1, included in a circuit, and as it makes the first rotary step the cam 34, which is attached to the same shaft, breaks contact with the spring 21, thereby allowing the latter to 40 in turn break contact with spring 24 and close contact with spring 20; and at the same time, this allows contact-arm 22 to make contact with the spring or switch-contact 23. The contact-springs or arms or switch-contacts 21 and 20, when brought together, 45 serve to establish a circuit from ground through relay-winding 36, which is on the same spool or magnet as the coil 16, through the corresponding winding 37 on the next 50 spool or magnet, and thence through all the corresponding coils of the other sixteen magnets shown in Fig. 1, through conductor 38, contacts 20 and 21, coil 25, conductor 26 to battery 11 and thence to ground. 55 Preferably, the windings 36, 37, &c., throughout all of the eighteen magnets, these windings being connected in series, are of such construction that the attractive power of their cores or pole-pieces is comparatively slight; so that armatures 14 and 13, which are, it will be remembered, already in contact with their respective pole-pieces or magnet-cores, will be retained in contact therewith; but none of the armatures of the sixteen relay-magnets will be attracted. The armature 29 of relay 25 will, however, be retained in contact with its pole-piece or magnet-core, thus maintaining 60 the continuity of the previously closed circuit through "rotary-magnet" 31 and its circuit-breaking contacts 32 and 33; and in this way, the said "rotary-magnet" will continue to rotate its shaft, and thereby keep the spring-wiper 35 moving until the latter has made a complete revolution. It will be seen, of course, that the cam 34 will also make a complete revolution simultaneously 65 with the said wiper, and will, as it returns to its starting point, again make contact with contact-arm 21, thus pressing the latter out of engagement with contact-arm 20, and again closing contact with the arm or spring 24; and this breaks the circuit just described from ground through windings 36, 37, &c. 70 in series through the other series relay-windings, through conductor 38, contacts 20 and 21, relay-coil 25, conductor 26 to battery and to ground. Instantly, upon the breaking of this circuit, relay-coil 25 will allow 75 its armature to return to normal position, thus breaking contact between said armature 29 and the contact 30, and thereby opening the circuit through "rotary-magnet" 31. At the same time, however, the said armature 14 of relay-coil 16 will return to its normal position in engagement with contact-point 27, and armature 13 of relay 15 will return 80 to normal position in engagement with contact-point 28. Obviously, however, and during the time that the spring-wiper 35 is making its revolution from starting point on contact 100, certain other operations will take place; and with respect to these additional electrical actions and operations, the 85 90 95 100 105 110 115 120 125 130

following preliminary explanation is made: For example, the wipers or switch-arms 101, 102 and 103, shown in Fig. 1, are diagrammatic representations of the spring-wipers 5 shown in Figs. 3 and 4, and hereinafter more fully described. These spring-wipers are mounted on a different shaft from the one on which the previously described spring 35 is mounted; but this second shaft is also 10 rotated, in a step-by-step manner, by means of the "rotary-magnet" 104 and its armature 107, which are shown in Figs. 1, 3 and 4. This "rotary-magnet" 104 actuates, through the medium of its armature, a pawl and 15 ratchet mechanism similar to that actuated by the "rotary-magnet" 31. Consequently, each time armature 107 is drawn down against its pole-piece or core, the pawl is drawn back sufficiently to engage a fresh 20 tooth on the ratchet-wheel, and as the armature is then released, the spring tension is such that the pawl pushes the ratchet-wheel forward or around until it strikes against the stop-screw 108. The adjustment and lo- 25 cation of the stop-screw 108 is preferably such that when the pawl rests against it, the ratchet-wheel, together with the shaft, is locked in such a position that the spring-wipers 101, 102 and 103 rest in contact with 30 one of the ten sets of contact-teeth arranged in semi-circle, as shown in Fig. 4. The method of fastening these wipers to the shaft, and of insulating them from each other, is shown in Fig. 7, and will be hereinafter more fully described.

Returning now to Figs. 1, 2 and 13, it will be seen that the ten sets of contact-teeth, such as set 109, 113 and 117; set 110, 114 and 118; set 111, 115 and 119, &c., are each connected with one of the ten automatic "preliminary-connectors" shown at the left in Fig. 2, and previously referred to. For convenience of illustration, only one set of these different connections is shown. The 45 contact-point 109 is shown connected with the conductor 121; contact-point 113 with conductor 122; and contact 117 with conductor 123. These three conductors lead to the so-called "preliminary-connector", or other suitable automatic switch, shown in Fig. 2, this so-called "preliminary-connector" being equipped only with "vertical" and "rotary" magnets 144^a and 145, together with a "release-magnet", and, of course, with armatures, pawls, stops, etc., suitable for giving the shaft a step-by-step vertical motion and a step-by-step rotary motion. As shown, the arrangement of circuits is such that spring-wipers 50 101, 102 and 103 will never rest, except for a brief instant, on a set of contacts connected with a "preliminary-connector" which is busy or already in use; and the circuits and means which prevent these wipers from 55 stopping on a set of busy contacts are as fol-

lows: Suppose, for example, that these wipers 101, 102 and 103 should, for any reason whatever, be moved about and so adjusted that wiper 101 would engage contact-point 109, wiper 102 in engagement with contact 113, and wiper 103 in engagement with contact 117, it being understood that these three contacts constitute one of the ten sets of contacts involved in the construction of the bank and switch-contacts shown in Fig. 4; 70 and also assume, for the purposes of this illustration, that the "preliminary-connector" K, shown in Figs. 2 and 13 (which is the particular "preliminary-connector" connected with these three bank-contacts) 75 should be found busy. In such case, the spring-contact-arm 124 of the said "preliminary-connector" will rest against the contact-point 125, thus closing connection between ground and contact 109 by means of 80 conductor 121, and thereby establishing a guarding potential at contact-point 109 by reason of its temporary connection with the grounded pole of the battery or other source of current. Consequently, when the wiper 101 engages contact-point 109, a circuit will be closed from ground through conductor 121, through contact-point 109, spring-wiper 101, conductor 126, contact-arms 106 and 105, and through coil 104 to battery 85 and to ground; and this will cause the "rotary-magnet-coil" 104 to attract its armature and, by means already described, induce the shaft to which spring-wipers 101, 102 and 103 are attached to instantly make one 90 100 rotary step, thereby carrying these wipers out of contact with points 109, 113 and 117, and into contact with points 110, 114 and 118. If these last-mentioned bank-contacts should be found busy, then the operations 105 just described would be instantly repeated, so as to carry the spring-wipers to another position. However, in order that a better understanding of the circuits may be had, it may be assumed that when the operator 110 or subscriber at telephone 51 starts to make the call, thus causing spring-wiper 35 to make a complete revolution over its contact-points, as already described, the wiper 101 is at such time resting upon contact-point 109; wiper 102 on contact-point 113; and wiper 103 on contact-point 117; that the "preliminary-connector-switch" K is in its 115 normal position and ready to receive a call from the switch-operating machine shown in Fig. 1. If these conditions prevail at the time the calling subscriber takes down his receiver, thereby causing wiper 35 to make a complete revolution over its bank-contacts—all of which is, of course, accomplished in an instant of time—the following operations will then take place: It will be remembered that when spring-wiper 35 moves from contact-point 100, cam 34 then moves away from contact-arm 21, thereby 120 125 130

permitting contact-arm 22 to engage contact-arm 23. As soon as this occurs, a circuit will be closed from ground through contact-arm 23, contact-arm 22, conductor 129, "rotary-magnet" 104 to battery and to ground. This, of course, will cause "rotary-magnet" 104 to attract its armature, and to retain the latter in its attracted position until spring-wiper 35 has completed its revolution, and thus permitting cam 34 to again come in contact with arm 21, and thereby open the circuit between contact arms 22 and 23. When this takes place, the "rotary-magnet" 104 releases its armature; then by means of the pawl and ratchet device already described, and hereinafter more fully explained, the spring-wipers 101, 102 and 103 will be moved forward one step, and onto contact-points 110, 114 and 118, so as to be ready for the next call sent in from the switch-operating machine; but these wipers will, of course, remain on contact-points 109, 113 and 117 during the time that spring-wiper 35 is making its revolution. Obviously, as spring-wiper 35 is given a step-by-step motion over its contact-points 100, 131, 132, 133, etc. throughout the sets of contacts in the bank, and just at the time when it rests on each new contact-point, it is connected to ground through conductor 134^a, contact-arm 33 and contact-arm 32. This, it will be seen, is for the reason that whenever the wiper 35 rests on a contact-point, armature 135^b is away from the core or pole-piece of its magnet; and each time armature 135^b is drawn up against its core or pole-piece, contact is thereby broken between arms 33 and 32, the result being that contact-arm or wiper 35, as it is stepped over its teeth, will also momentarily be connected to ground as it rests on each tooth in its path of travel. The effect of this action will be readily understood; for as contact-arm or wiper 35 rests on contact-point 131, a circuit will thereby be closed from ground through contact-arm 32, contact-arm 33, conductor 134^a, contact-arm or wiper 35, contact-point 131, conductor 144, "vertical-switch-wiper" 103, contact-point 117, conductor 123, "vertical-magnet" 144^a (Fig. 2), conductor 146 to battery 11 and to ground. The closure of this circuit results, of course, in the sending of one impulse through "vertical-magnet" 144^a, causing the latter to raise the shaft of switch K one step. The switch-wiper 35, of course, passes onto contact 132, where it again closes a circuit, and sends another impulse through "vertical-magnet" 144^a of the said "preliminary-connector-switch" K. This latter circuit is from ground through wiper 35, contact-point 132, conductor 136^a, contact-point 147, contact-arm 140, conductor 135^a, conductors 144 and 128, "vertical-switch-wiper" 103, contact-point 117, thence through conductor 123 to "vertical-magnet" 144^a of the switch K and to battery. At such time, the spring-wiper 35 passes on to contact-point 133, where it effects the transmission of another impulse through "vertical-magnet" 144^a, the circuit at this time being closed through contact-point 133, conductor 137^a, contact-point 148, armature 141, contact-point 147, armature 140, conductor 135^a, contact-point 131, conductors 144 and 128 to "vertical-wiper" 103, etc., as before. In this way, and as wiper 35 passes on to contact-point 134, another electrical impulse is transmitted through "vertical-magnet" 144^a; and this time the circuit includes the contact-point 134, conductor 138^a, contact-point 149, armature 142, contact-point 148, armature 141, contact 147, armature 140, conductors 135^a, 144 and 128, "vertical-wiper" 103, etc. The spring-wiper 35 moves onto contact-point 135, where it again effects the transmission of an electrical impulse through contact-point 135, conductor 139, contact-point 150, armature 143, contact-point 149, armature 142, contact-point 148, armature 141, contact-point 147, armature 140, conductors 135^a, 144 and 128, "vertical-wiper" 103, etc.; it being understood that from this point on each circuit through the "vertical-magnet" 144^a is the same as the others. As stated, spring-wiper 35 moves into contact with the switch-point 136; but from this point it will not, and cannot, effect the transmission of another "vertical" impulse through the "vertical-magnet" 144^a. This, of course, is due to the fact that armature 13 of coil 15 is, at such time, drawn up, thereby breaking contact with contact-point 28, so that spring-wiper 35 will then and from there be incapable of effecting the transmission of further "vertical" impulses, and will cause the transmission of no impulse or impulses of any kind whatever until it passes from contact-point 137 onto contact-point 138; and when this happens it will commence to send "rotary" impulses over the "rotary-line" to the "rotary-magnet" 145 of the "preliminary-connector-switch" K.

It will now be seen that five impulses, corresponding to the first digit of the number of the calling subscriber, have now been transmitted through "vertical-magnet" 144^a of the "preliminary-connector-switch" K, thus raising the wipers of this "preliminary-connector" to the proper levels—that is to say, the points where these wipers will be opposite the fifth row of contact-teeth, and thus made ready for entering their levels as soon as "rotary" impulses are sent through the said "rotary-magnet" of the switch; and it will be seen that a "rotary" impulse is transmitted as soon as the spring-wiper 35 reaches contact-point 138, a circuit being thereby momentarily closed as follows:

From ground through contact-arm 32, contact-arm 33, conductor 134^a, spring-wiper 35, contact-point 138, conductor 127, "rotary-wiper" 102 of the switch-operating machine, 5 contact-point 113, conductor 122, "rotary-magnet" 145, conductor 146 to battery 11 and to ground; thus causing a single "rotary" impulse to be sent through the "rotary-magnet" 145, the construction of which latter is, as will hereinafter more fully appear, such that it causes the switch-shaft of the "preliminary-connector" to make one rotary step, thus causing the shaft-wipers 151 and 152 to be brought into contact with the 10 switch-points 154 and 153 of the bank of contacts allotted to this switch; and also causing "private-wiper" 155 to be placed in electrical contact with the tooth or contact-point 156 of the so-called "private-bank" of 15 this switch. At this time, it will be seen that the "preliminary-connector-switch" K has completed its operation, having placed the "line-wipers" 151 and 152 on the first set of contacts of the fifth row or level in 20 the bank of "line-contacts", it being observed that this bank is made up of pairs of contacts, each pair consisting of two contacts connected with the opposite sides of a subscriber's line. In other words, connection 25 is made with the set of contacts which correspond to the number of the calling subscriber, thus completing the connection from the lines coming in from telephone 51 through conductors 157 and 158, line-wipers 30 151 and 152 to trunk-line-conductors leading to a regular first "selector-switch", or, as shown in Fig. 15, to an ordinary "connector-switch", or to any other suitable switching apparatus. At this time, it will 35 be seen that a circuit is also established through the bridge-cut-off-relay 159 (Fig. 2), this circuit being from ground through "private-wiper" 155, contact-point 156, through relay-coil 159 to battery 11 and to 40 ground; thus causing the core of coil 159 to attract the armature 159^a, and effecting the retention of this armature in its attracted position until the "preliminary-connector-switch" K is finally released and restored to 45 its normal condition, after the conversation has been terminated. When the bridge-cut-off-relay 159 attracts its armature—it being understood that one of these bridge-cut-off-relays can be allotted to and made individual 50 to each subscriber's line—it breaks contact between the switch-springs or contacts 8, 9 and 10, thus opening the bridge normally closed across the line-conductors 1 and 2 leading from telephone 51, and which bridge 55 includes the "line-relay" coils or windings 6 and 7 connected normally to battery through the said contact-arms; and this leaves the line of the calling subscriber free from bridges of this character, and puts the 60 line in condition for subscriber 51 to operate 65

the regular first "selector", second "selector", third "selector", etc., and the regular and usual "connector"; or, as stated, the calling subscriber may then simply operate a "connector-switch", as shown in Fig. 15, and 70 secure direct connection with the line of the called subscriber without using any "selectors" whatever. It will also be seen that the wiper 35, after leaving contact-point 138, passes on, in the manner previously 75 described, until it again returns to contact-point 100; and at the same time cam 34 also returns to its original position, thus pressing contact-arm 21 away from contact-arm 20 and into engagement with contact-arm 24, 80 and also breaking contact between the arms 23 and 22. Obviously, with the arrangement shown, the contact 21, as it breaks away from the arm 20, serves to open the 85 previously described circuit from ground to coils 36 and 37, and all of these coils in series, as shown in Fig. 1; and this action having been accomplished, armature 14 returns, of course, to its original position in engagement with the contact-point 27, while armature 13 of coil 15 returns to its original 90 position in engagement with contact-point 28. It will be seen, however, that this circuit also includes the relay-coil 25 and, consequently, that the latter releases its armature, thereby breaking contact between contact-arm 29 and contact-point 30, and in 95 this way opening the circuit from ground through "rotary-magnet-coil" 31. This, of course, results in bringing the wiper 35 to 100 rest on contact-point 100, where it remains until a new call is sent in from any other telephone of this particular group of subscribers, or from any other subscriber in the exchange, providing the size of the exchange 105 is of a character indicated in the drawings. It must be borne in mind, however, that another circuit is broken or opened up—that is to say, the circuit through "rotary-magnet" 104—owing to the separation of 110 contacts 22 and 23; and consequently magnet 104 releases its armature, whereupon the pawl of armature 107 engages the shaft carrying the spring-wipers 101, 102 and 103, and thus moves the latter into engagement 115 with the points 110, 114 and 118, ready to receive the next call coming in from the calling wiper 35 in response to the removal of a telephone-receiver from its hook by some other subscriber, or in response to current transmitted in any other suitable manner for the purpose of bringing about the connecting operations which are of a more or less preliminary character, and which must take place before the electrical impulses 120 representing the digits of the called number are permitted to flow through the relays or magnets of a "selector-switch" or "connector-switch", or both, as the case may be.

The method of calling the desired number 125

may be as follows: In Fig. 14 the "connector" mechanism is shown, and in Fig. 15 this "connector" is shown in use between the two subscribers' stations. After subscriber 51 has, in the manner previously explained, obtained connection with the trunk-line L leading to the idle "connector-switch," the calling subscriber then operates his calling device, such, for example, as the keys or buttons 10 a^{16} and a^{17} ; it being understood, of course, that in practice the calling device may be of any suitable, known or approved construction, and that the said keys or buttons are simply shown as a matter of convenience of illustration. When the key or button a^{16} is pressed, it is obvious that the line-conductor 2 will be connected through contact-point a^{18} , conductors a^{19} and a^5 , contacts a^6 and a^7 , to ground at a^8 ; and in a similar manner, when the key or button a^{17} is pressed, the line conductor 1 is connected to ground through contact a^{20} , and thence through the same conducting path just described in connection with the grounding 25 of line-conductor 1. In Fig. 15 A represents the apparatus of the calling subscriber, and B that of the called subscriber. The heavy lines represent the talking circuit—that is to say, the circuits for the voice currents. The relays and other devices included between the broken lines 1—1 and 2—2 belong to the "preliminary-connector" in use between the two subscribers' lines. The relays, magnets and switching devices, etc., 30 included between the broken lines 2—2 and 3—3 belong to the "connector" which is shown in use between the two lines. The devices shown at the left of line 1—1 are individual to the calling subscriber's line. In a similar manner, the devices shown at the right of line 3—3 are individual to the line of the called subscriber. If the number 35 of the called subscriber is 99, the calling subscriber will first press the switch-key a^{17} nine times, thereby sending nine distinct impulses over the "vertical" line-conductors 1 and 157, and through the "vertical-relay" m^{84} , by reason of the connection thus brought about between the conductor L and the ground at a^8 , and the said relay and the non-grounded pole of battery 11 through the medium of suitable conductors, as shown, for example, in Fig. 15. The "vertical-relay" in turn closes the circuit nine times, 40 which includes the battery 11, the "vertical-magnet" m^{23} , "side-switch-wiper-contact" m^{97} , wiper m^{68} , contact-springs m^{54} and m^{52} , and contact-springs m^{90} and m^{92} to ground at m^{93} and back to battery. The first impulse releases the locking-dogs of the "connector," because the hook m^{27} lifts the "release-link" m^{19} off the pin m^{17} , and the nine distinct impulses cause the shaft to be stepped up to the ninth level of bank-contacts, thus bringing the "private-", "vertical" and "rotary" shaft-wipers into the desired position. The calling subscriber then presses the switch-key a^{16} once, so as to ground the "rotary-line-conductor" but once, thus sending a single impulse through the "private-magnet" m^{40} of the "connector." 45 This magnet, when energized and then de-energized, permits the finger m^{58} to escape one tooth, under the influence of the spring m^{59} , and to thereby shift the "side-switch-wipers" from first to second position. The calling subscriber then again presses the switch-key a^{17} nine times, so as to send nine distinct impulses over the "vertical-line-conductor" L; but this time, owing to the shifting of the wiper m^{68} onto the contact m^{68} , the said impulses energize the "rotary-magnet" m^{84} owing to the circuit arrangement provided and illustrated in Fig. 14. The nine rotary impulses thus given the 50 shaft m of the "connector" by the said "rotary-magnet" bring the wipers m^1 , m^2 and m^3 into the desired position—that is to say, into correct position for making connection with the "line" and "private" normals connecting with the line of the called subscriber, as shown in Fig. 15. After this, the calling subscriber again presses the switch-key a^{16} once, and thereby again energizes and de-energizes the "private-magnet" m^{40} of the "connector." The said "private-magnet" permits the finger m^{58} to escape and move outwardly until it strikes the stop m^{60} , the movement of this "side-switch" having been limited the first time by the engagement of the projection m^{121} with the cam m^{11} . The final operation of the "side-switch," in this manner, moves the "side-switch-wipers" from second position to third position, thus connecting the line-conductors 55 L with the conductors leading to the "vertical" and "rotary" wipers m^2 and m^3 , which latter are now in engagement with the bank-contacts connected with the "line-normals" leading to the line of the called subscriber. The final action of the "side-switch" in this manner also makes it possible, by pressing the key a^{12} , to connect the ground a^8 with the "vertical-line conductor" L of the calling subscriber's line, and to thereby throw ringing current onto the completed line-circuit between the two subscribers by reason of the engagement of the wiper m^{68} with the third contact m^{69} . When the calling subscriber 60 presses the ringing-key in this manner, a circuit is formed from ground, as stated, through the conductors 1 and 157, through the "vertical-line-relay" m^{84} to battery 11, and then to ground; and this will, of course, bring the springs m^{90} and m^{92} together, thereby closing a circuit from ground m^{93} through springs m^{52} and m^{54} , through the wiper m^{68} , through the ringing-relay m^{104} , and thence to the non-grounded pole of the battery. The ringing-relay thus energized 65

attracts its armature and, in so doing, opens the line-circuit existing between the two subscribers' lines, and simultaneously therewith bridges the ringing-generator m^{12} 5 across the circuit. The ringing current thus projected onto the called subscriber's line rings the bell at station B. During the calling of the desired number, it will be seen that the impulses sent over the "vertical-line" l 10 energize the "vertical-relay" m^{84} , thus closing the local circuit including the "vertical-magnet" m^{23} , as shown in Fig. 14; and in this way, the line impulses are repeated, so to speak, from the line-circuit to a local 15 circuit including the "vertical-magnet." In a similar way, the electrical impulses sent over the line-conductor 2 are repeated by the "rotary-line-relay" m^{85} to a local circuit including the "private-magnet" m^{24} , as also 20 shown in Fig. 14. As explained, however, the next group or set of impulses sent over the "vertical-line" are repeated by the "vertical-line-relay" m^{84} to a local circuit including the "rotary-magnet" m^{24} by reason of 25 the shifting of the "side-switch" in the manner explained. The final impulse sent over the "rotary-line" is repeated by the "rotary-relay" to the local circuit including the "private-magnet," so as to accomplish the shifting 30 of the "side-switch" to third position, as set forth, and by reason of the circuit arrangement shown more clearly in Figs. 14 and 15. The engagement of the "private-wiper" m^1 with a contact connected with the 35 bridge cut-off relay of the called subscriber's line brings about the energizing of such relay, thereby removing the bridge from this part of the circuit. In addition, the "private-wiper" m^1 , being now connected with 40 the grounded contact m^{72} , sets up a guarding potential at the multiples of the contact with which it remains in engagement during conversation between two subscribers; and in this way, no other "connector" 45 can be operated by other subscribers in such manner as to make connection with any bank-contacts connected with the called subscriber's line. Also, while the two subscribers are talking, the grounded wiper 155 sets up a guarding potential at all of the "connector" bank-contacts allotted to and connected with the line of the calling subscriber. In this way, the "private-shaft-wipers" of both the "connector" and the 50 "preliminary-connector" have a double function, so to speak, inasmuch as they complete circuits for energizing the bridge cut-off relays, and, in addition, connect the multiple "private-bank-contacts" of the subscribers' lines with the grounded pole of the 55 battery, so as to prevent seizure of either the calling or called lines while the two subscribers are talking. Should the line of the called subscriber be busy when the calling 60 subscriber sends the impulses representing 65 the last digit of the called number, it is evident that the "connector" will be instantly and automatically released. This is for the reason that when the "private-wiper" m^1 engages a busy contact, the "side-switch" being still in second position, a circuit is immediately formed from ground over the "private-normal" connected with the busy line, through the "private-wiper" m^1 , through the "side-switch-wiper" m^{85} , 70 through the springs m^{53} and m^{55} , the "private-magnet" having been energized by the final single impulse, thence through the "release-magnet" m^{79} to the non-grounded pole of the battery 11. The "release-magnet" being energized in this manner, the locking-dogs are withdrawn from engagement with the ratchet-teeth, and the switch-shaft permitted to assume its normal position. 75 When the calling subscriber then presses his 80 ringing-key, the single impulse thus transmitted, instead of ringing the called subscriber's bell, energizes the "vertical-relay," and thus effects the energizing of the "vertical-magnet"; and with the result that the 85 shaft is given one vertical step. This, it will be seen, is sufficient to close together the contacts m^1 and m^8 , and to thereby close a busy signal circuit leading from the busy 90 signal machine W (Fig. 15) through the 95 said contacts, and through the "side-switch-wiper" m^{84} to the "rotary" line-conductor 2, through the calling subscriber's receiver and back over the other side of the circuit, in the well-known manner. But if the called subscriber's line is not busy, the connection between the two lines will be made, and the 100 circuits completed in the manner shown in Fig. 15. 105 The method of releasing the switches, after the subscribers are through talking, is as follows: Either subscriber can release the switches, but it will be sufficient to assume that the release is made by the subscriber at station 51. In such case, subscriber 51, who was the calling subscriber, simply replaces his receiver a^{10} on the switch-hook a , thereby causing the switch-hook projection a^{21} to press the three normally-separated contacts a^{22} , a^{23} and a^{24} together, thereby completing a connection from both sides of the line to ground through the conductor a^5 , as shown in Fig. 12. 110 115 This energizes the "vertical" and "rotary" line-relays of the "connector," by reason of the circuit arrangement shown and described, and thus closes a circuit from the non-grounded pole of the battery 11, through suitable conductors, through the "release-magnet" m^{79} , through the springs m^{88} and m^{89} , through the "release-relay" h to ground, and thence back to battery. The said "release-magnet" and the 120 said "release-relay" being thus energized, the mechanism of the "connector" is released 125 130

in the manner described, and a local circuit is also closed at the calling "preliminary-connector"; and this local circuit includes the "release-magnet" k^1 , which promptly releases the mechanism of the said "preliminary-connector." The two switches having been thus restored to their normal positions, the apparatus is then ready for use in making other connections. The called subscriber 10 may also disconnect the connector from his own line by replacing his receiver upon the switch-hook, and thereby momentarily grounding both sides of his line in the manner described in connection with switch A. 15 When this is done, the "back-release-relays" m^{96} and m^{97} are energized, by reason of the circuit arrangement shown, these two relays, while the subscribers are talking, remaining bridged across the circuit with their middle 20 points connected to the non-grounded pole of the battery 11. When these two relays are energized, they attract their armatures and thereby effect the closure of circuits including the "release-magnet" m^{79} . It will 25 be seen that this circuit, as shown in Fig. 14, extends from ground m^{103} through the springs m^{101} and m^{100} , through the release-magnet m^{79} to the battery 11 and to ground again. This, of course, effects the release of 30 the connector, and restores the latter in the manner already described. In this way, the "private-magnet" m^{40} of the "connector" is only used for releasing purposes when an 35 automatic release is to be brought about by reason of the engagement of the shaft-wipers of the "connector" with busy contacts.

It has been shown how a one-hundred-exchange subscriber operates the apparatus 40 to establish connection with a second subscriber. It will now be pointed out how a connection is established in a one-thousand system. Upon referring to Fig. 17 it will be seen that the trunk conductors $L-L$ of 45 the "preliminary-connector-switch", or "pre-selector", lead to the first "selector-switch" N, instead of to the "connector-switch" M as shown in Fig. 15. It will be seen that the trunk conductors L^1 and L^2 which lead 50 from the banks of the first "selector-switch" N, and which are similar to the conductors $L-L$, terminate in the "connector-switch" M (Fig. 15). If the subscriber A (Fig. 17) desires to establish connection with the subscriber B, whose number, it will be assumed, 55 is 299, the central office switches are operated in the following manner: When the calling subscriber's receiver is removed from the switch-hook a "preliminary" impulse is 60 transmitted to the line-conductor 1, and a "preliminary-connector" is operated, as explained, to establish connection with the line-conductors 1 and 2 and thus extend the substation conductors to the first "selector-switch" N. When the subscriber oper-

ates the calling device for the first digit 2 the "vertical" line-conductor 1 is grounded twice and the "rotary" line conductor 2 is grounded once. The grounding of the "vertical" line-conductor closes a circuit through 70 the "vertical-line-relay" n^{16} of the first "selector-switch", said circuit extending from ground a^8 through the push-button spring a^{17} , conductors 1 and 157, shaft wiper 152, conductor L, "side-switch" n^5 , contact-point n^{24} , through the "vertical-line-relay" n^{16} to the battery lead, thence through battery 11 to ground. The "vertical-line-relay", upon energizing, operates to close the springs n^{18} and n^{19} in contact, whereby a 80 circuit is closed through the "vertical-magnet" n^1 . The "vertical-magnet" operates in the usual manner to carry the shaft-wipers n^{11} , n^{12} and n^{13} up two steps to a position opposite the second level, in which are located the terminals of trunk lines leading to "connector-switches". When the key or button a^{19} is pressed, the "rotary" line-conductor 2 is grounded and an energizing current flows through the "rotary-line-relay" n^{17} 85 extending from ground a^8 through the key a^{16} , conductors 2 and 158, shaft-wiper 151, conductor L, "side-switch-wiper" n^6 , contact-point n^{25} , through the "rotary-line-relay" n^{17} to the battery lead, thence through battery 11 to ground. The "rotary-line-relay", upon energizing, presses the springs n^{18} and n^{20} into contact, which in turn closes a circuit through the "private-magnet" n^4 . 90 The "private-magnet", upon energizing and de-energizing, permits the "side-switch-wipers" to pass from first to second position. When the "side-switch-wiper" n^7 engages the contact-point n^{26} an energizing circuit is 95 established through the "rotary-magnet" n^{14} , and the said magnet operates in the usual manner to carry the shaft-wipers n^{11} , n^{12} and n^{13} to the contacts of the first idle trunk line which, it will be assumed, is the line 100 having the conductors L^1 and L^2 . When the subscriber operates the calling device for the last two digits 9 and 9, the "connector-switch" M (Fig. 15) is operated, in a manner previously explained, to establish 105 connection with the "normal-conductors" 110 leading to substation B. The two substations are thus connected, and conversation may be carried on over the circuit indicated by the heavy lines in Figs. 17 and 15. One 115 difference in the arrangement of the central office switches in the one-thousand system and the one-hundred system, previously explained, is the adding of the first "selector-switch" N between the "preliminary-connector" and the "connector-switch" M. The 120 release of the central office switches is brought about when the calling subscriber restores the receiver to the switch-hook, thereby grounding both line-conductors 1 and 2 and simultaneously energizing the 125 130

"vertical" and "rotary" line-relays m^{64} and m^{65} of the "connector-switch" M , which operate to close an energizing circuit through the "release-relay" n^{73} of the "selector-switch" N in series with the "release-magnet" n^{79} of the "connector". The "connector-release-magnet", upon energizing, operates as usual to restore the switch. The "release-relay" n^{23} , upon energizing, operates to close an energizing circuit through the "release-magnet" n^3 of the "selector" N in series with the "release-relay" k of the "preliminary-connector-switch". The "release-relay" k operates to in turn close an energizing circuit through the "release-magnet" k^1 . The release magnets and relays thus energized, de-energize and operate to restore their respective switches to normal position when the ground connection to the line-conductors 1 and 2 is removed.

When the central office is arranged as a ten-thousand system, a second "selector-switch" E (Fig. 18) is added, and the number of the called subscriber B may be assumed to be 2299. The calling subscriber A operates the "preliminary-connector" and the first "selector-switch" N in the usual manner; but the "selector-switch" N , instead of selecting trunk lines leading to "connector-switches", now selects trunk lines L^1 and L^2 which lead to the second "selector-switch" E (Fig. 18), and the second "selector-switch" E in turn operates to select the trunk line conductors L^3 and L^4 which lead to the "connector-switch" M . The grounding of the line-conductors 1 and 2 for the second digit of the number 2299 operates the second "selector-switch" E to extend the substation conductors 1 and 2 to the trunk line conductors L^3 and L^4 leading to the "connector-switch" M (Fig. 15), and the "connector-switch" is in turn operated by the impulses for the last five digits to extend the connection to the "normal-conductors" of the line 1-2 of substation B . The connection extends through the "connector-switch" M which appeared in the one-hundred system, through the first "selector-switch" N which was added for the one-thousand system, and through the second "selector" E which is now added for the ten-thousand system.

When the central office is arranged on the one-hundred-thousand basis a third "selector-switch" O is added to the series of switches employed in the ten-thousand system. The numbers of the subscribers' substations must contain five digits, since there are three numerical switches, besides the connector, to be operated by the calling subscriber. It will be assumed that the number of the called subscriber's line is 22299. The calling subscriber A (Fig. 17) operates the "preliminary-connector" and the first "selector-switch" N in the usual

manner. The "selector" N is then operated for the first digit (2) to select trunk-line-conductors L^1 and L^2 which lead to a second "selector-switch" E (Fig. 18) and the second "selector" E is in turn operated for the second digit (2) to select the trunk-conductors L^3 and L^4 which lead to the third "selector-switch" O (Fig. 19). As the subscriber continues the call the "selector-switch" O is operated for the third digit (2) to select an idle trunk-line L^5 and L^6 which terminates in the "connector-switch" M . The grounding of the line-conductors 1 and 2 by the calling subscriber for the last two digits (9 and 9) operates the "connector-switch" M in the usual manner to extend the connection to the normal-conductors 1 and 2 of the substation B . The two substations A and B are now connected, the connection extending from the substation A over the conductors 1 and 2, through the "preliminary-connector" or "preselector" K to the first "selector-switch" N (Fig. 17), through the second "selector" E (Fig. 18), third "selector" O (Fig. 19), and finally through the "connector-switch" M to the line-conductors 1 and 2 which lead to the desired substation.

The release of the central office switches is brought about when the calling subscriber restores his receiver to the switch-hook, thereby grounding both line-conductors and simultaneously energizing the "vertical" and "rotary" line-relays of the "connector-switch" M , which operate to close a series energizing circuit through the "back-release-relay" e^1 of the "selector-switch" E and the "release-magnet" m^{79} of the "connector". The "release-relay" e^1 , upon energizing, operates to close an energizing circuit through the "release-magnet" e^2 of the "selector" E in series with the "release-relay" n^{23} of the first "selector" N . The "selector-release-relay" n^{23} then operates to close a circuit through the "release-relay" k in series with the "release-magnet" n^3 , and the "release-relay" k , upon energizing, in turn operates to energize the "release-magnet" k^1 of the "preliminary-connector". All the magnets and relays involved in the release remain energized until the ground connections to the line-conductors is removed.

The "connector" shown in Fig. 14 is of the type described and shown in patent No. 515,173, granted March 13, 1903, to Keith, Erickson & Erickson. The "preliminary-connectors" herein described are also similar, as far as mechanical construction and mode of operation is concerned, to the switch shown in this patent. The subscribers' apparatus, particularly the calling arrangement, or switching device for operating the different switches, is of the therefore well-known Strowger type, the usual impulse-sending apparatus being represented dia- 130

grammatically by the push buttons a^{16} and a^{17} .

The mechanical construction and the electrical circuit arrangement of the switch-operating machine shown in Fig. 1, and also illustrated in Figs. 3 to 10, inclusive, is as follows: It will be observed that telephone 51 is simply one of a group of one hundred telephones or one hundred subscribers' stations, or of any smaller number, eighty-one being the number of telephones or subscribers' stations indicated in Fig. 1. In this diagram, it will be seen that the smallest number for any station is eleven, while the highest number is ninety-nine; and it will also be seen that only the three contact-arms, corresponding to the contact-arms 3, 4 and 5, are shown for each telephone or subscriber's station, it being understood that a "line-relay" is associated with each of these eighty-one sets of contact-arms. Furthermore, it will be seen that the relays 160 and 164, and all of those between these two relays, constitute what may be called the "vertical-relays" of the switch-operating machine, inasmuch as they control the different circuits over which the "vertical" impulses are transmitted by the said machine for operating the "vertical-magnets" of the "preliminary-connectors". On the other hand, the relays 16 and 168, and all of the relays between these two particular double wound relays, constitute what may be called the "rotary-relays" of the switch-operating machine, inasmuch as these particular relays control the different circuits over which the said machine transmits the "rotary" impulses for operating the "rotary-magnets" of the "preliminary-connectors". Consequently, the nine relays to the right of the line X—Y represent the first digits of the numbers of the subscribers in this particular group, while all of the relays at the left of said line represent the second digits of the said numbers. For example, if subscriber 11 takes down his receiver, the result of such act would be the energizing of relays 16 and 160—that is to say, of the inner coils of these two relays; and in such case, the switch-operating machine will first send one "vertical" impulse and then send one "rotary" impulse, thereby in effect calling the number of the calling subscriber. Again, should subscriber 99 remove his receiver from the switch-hook, the result would be the energizing of relays 168 and 164, and in this case the switch-operating machine will first transmit nine "vertical" impulses to the idle or waiting "preliminary-connector", and then nine "rotary" impulses. In other words, each relay at the left of line X—Y is common to nine subscribers whose numbers all terminate with the same digit, as, for example, relay 16 is common to all subscribers whose numbers terminate with the digit one. In a similar manner, each relay at the right of line X—Y is common to nine subscribers whose numbers all begin with the same digit, as, for example, relay 160 is common to all subscribers in the group whose numbers begin with the digit one. With this arrangement, the first "vertical-relay" cooperates with the first "rotary-relay", or with any other relay at the left of line X—Y, according to the number of the calling subscriber; and in like manner any other relay at the right of line X—Y co-operates with any relay at the left of such line, according to the number of the calling subscriber. Invariably, then, if the first digit of the calling subscriber's number is five, for example, the taking down of the receiver at this subscriber's station will result in the energizing of the inner coil of the fifth "vertical-relay"; but if, in any case, the first digit of the calling subscriber's number is eight, for example, then the eighth "vertical-relay" will be energized. On the other hand, and invariably if the second digit of the calling subscriber's number is five, the result will be the energizing of the fifth "rotary-relay"; but if this second digit is eight, for example, then the eighth "rotary-relay" will be energized. In any case, however, it will be seen that the energizing of a certain "vertical-relay", for example, makes it possible for only a certain number of the "vertical-contacts" to receive and transmit impulses from the wiper 35 to the "vertical-magnet" of a "preliminary-connector"—the number of contacts thus remaining operative corresponding to the number of the energized "vertical-relay", and all of the "vertical-contacts" above such number being rendered inoperative to transmit impulses when engaged by the said wiper. This is also true, of course, with respect to the said "rotary-relays", inasmuch as the energizing of any particular "rotary-relay" cuts out, so to speak, all of the "rotary-contacts" above the number of such "rotary-relay"—that is, if the third "rotary-relay" is energized, only the first three "rotary-contacts" will remain operative, while the other seven will be rendered inoperative by reason of the gap or break produced in the circuits. It will be seen that the "line-relay-contacts" allotted to and employed for closing a ground connection through any particular "vertical-relay" are all multiplied together by means of one of the "horizontal" conductors shown in Fig. 1. In a similar manner, the "line-relay-contacts" which are allotted to and employed for closing a ground circuit through any particular "rotary-relay" are all multiplied together by means of one of the "vertical" conductors shown extending at right-angles to the said "horizontal" conductors.

Evidently, therefore, each subscriber's line in the group is provided with a double wound "line-relay", such as shown in Fig. 2, and with a bridge-cut-off-relay and switch-contacts operated thereby, such, for example, as the contacts 8, 9, and 10; and for each "line-relay" there are three normally separated contacts, such, for example, as the contacts 3, 4 and 5. These line and bridge cut-off relays can, of course, be placed in any convenient or advantageous position, as, for example, on a relay-rack of suitable construction. In any case, however, the subscribers' lines are preferably divided in groups of one hundred, or, if the arrangement were exactly as shown in the drawings, in groups of eighty-one subscribers each; and, as shown and described, one group or set of eighty-one subscribers might, of course, constitute an entire exchange. As previously stated, this group of eighty-one subscribers would have in common nine "vertical-line-relays", and also nine "rotary-line-relays"; and the same group would also have in common one switching mechanism, such as shown in Figs. 3 to 10, inclusive, and the circuit construction of which has already been described. Referring more particularly to Fig. 3, it will be seen that the switch-operating machine comprises a suitable frame or body F adapted to provide bearings and supports for the various magnets and operative parts. For example, the shaft S, which carries the wiper 35, is supported in bearings s. This shaft, as previously explained, is provided with a ratchet-wheel s¹ adapted to be actuated by the pawl s², which latter is pivotally mounted on the armature 135^b of the "rotary-magnet" 31. Referring to Fig. 8, it will be seen that this pawl is limited in its forward thrust or movement by means of an adjustable stop-screw s³ inserted through the portion f of the said body or frame. A spring locking-dog s⁴ also engages the said ratchet-wheel, and thereby prevents back rotation of the shaft S. The pawl s² is pivoted at s⁵ to the upper end of the armature-arm s⁶, and is subject to suitable spring tension for holding it in engagement with the ratchet-teeth, and for permitting it to slide backward over the said teeth; and the said armature 135^b is provided with a spring s⁷ so applied that the said armature is normally away from the magnet 31, this spring s⁷ also constituting the means for positively actuating the ratchet device; for the pawl is attracted when the magnet is energized, and the ratchet-wheel rotated when the armature is released.

The spring-wiper 35 is adapted to describe a circle, and in so doing to slide over the contact-teeth or switch-contacts which are arranged in a circle, as previously de-

scribed, and which are each provided with a terminal s⁸ for making the necessary connections with the conductors leading to the contacts of the "vertical" and "rotary" relays. Preferably, the said spring-wiper is secured to an insulated hub s⁹ on the shaft S, said hub being engaged by a brush or spring-arm s¹⁰; and with this arrangement it will be seen that the conductor 134^a (Fig. 1) can be secured to the terminal of the brush s¹⁰, and that in this way the necessary current from the ground pole to battery 11 is conveyed to the wiper 35 without including the shaft S in the circuit. The armature 135^b also carries the insulated interrupter-arm s¹¹, which latter is adapted to operate the previously-described circuit-opening and closing springs 32 and 33; the said interrupter-arm being provided at its end with a lateral projection s¹², adapted, when the armature is attracted, to first engage the intermediate spring s¹³ (see Fig. 11) and to then pass between this spring and the outer end portion of the spring 32, so as to press the outer end of spring 33 away from out of engagement with the end of the spring 32, it being observed that a piece of insulation s¹⁴ separates the springs s¹³ and 33. When the armature is released, the portion s¹² again passes between the ends of the springs s¹³ and 32, thereby preventing the springs 33 and 32 from re-engaging each other until after the armature has been completely restored to its normal position. It will be understood, however, that any other suitable, known or approved arrangement can be employed for producing an intermittent energizing of the "rotary-magnet" 31. As previously explained, the cam 34 is also mounted upon the shaft S, this cam being practically made of hard rubber or other insulating material. With the arrangement shown, this cam is substantially round in character, being provided with only a single projection or node s¹⁵, as shown in Fig. 9. Normally, this projection or node engages the spring 21 for the purpose of keeping the springs 21 and 20 normally separated, and also for the purpose of keeping the springs 22 and 23 normally separated, as shown in Figs. 1 and 9; and it will also be seen that springs 21 and 24 are normally in engagement with each other. The said cam 34 rotates in the direction indicated by the arrow and, after releasing the said springs, makes a complete rotation, in unison with the wiper 35, before again engaging the said springs and returning the latter to their normal condition. Again referring to Fig. 3, it will be seen that the shaft I is supported in bearings i and arranged parallel preferably with the shaft S. As previously explained, the spring-wipers 101, 102 and 103 are all mounted upon this shaft I, and, as shown

more clearly in Fig. 7, are all insulated from each other and from the said shaft; but it will be readily understood that these wipers revolve in unison with the said shaft. The "vertical-bank-contacts" of the "vertical-wiper" 103 are provided with terminals i^1 ; the "rotary-bank-contacts" of the "rotary-wiper" 102 with terminals i^2 ; and the "private-bank-contacts" of the "private-wiper" 101 with terminals i^3 . These "vertical", "rotary" and "private" bank-contacts are arranged as shown more clearly in Fig. 4, and are, of course, all insulated from each other, the removable bank thus formed being removable as a unit and formed on the arc of a circle. Consequently, the said wipers 101, 102 and 103 are preferably double ended, so to speak, each wiper being provided with opposite ends adapted to engage and travel upon its allotted contacts. In this way, each wiper is adapted to revolve in the direction indicated by the arrow in Fig. 4, and is adapted with one end to re-engage its allotted series or row of contacts immediately after disengaging the last contact in such row or series with its other end—that is to say, the opposite ends of each wiper are alternately brought into engagement with the contacts, the arrangement being such, however, that while one end is in use, the other end is out of use. The wiper 103 is insulated from the shaft and from the other wipers, but is in electrical contact with the metal hub or collar 103^a. In this way, a brush or spring-contact 103^b, which bears upon the said hub or collar, is employed for furnishing current to the said wiper. The arrangement of the other two wipers is practically the same, the wiper 102 being provided with a hub or collar 102^a and a brush or spring-contact-arm 102^b; and the "private-wiper" 101 is provided with a hub or collar 101^a engaged by a brush or spring-arm 101^b. As previously explained, these wipers 101, 102 and 103 all rest upon contacts of the semi-circular bank I¹; and, consequently, the wipers of this switch are always in electrical connection with a trunk-line, either busy or non-busy, and with the "preliminary-connector" at the end of such line. The motive power or propelling means for rotating the shaft I consists, as previously explained, of the "rotary-magnet" 104, the armature 107, the pawl 108^a, and the ratchet-wheel i^4 . The said armature is suitably mounted and pivoted at i^5 , and the said pawl is pivotally secured at i^6 to the upwardly-projecting arm of said armature. Spring means i^7 , of any suitable character, are employed for keeping the pawl fixed against the teeth of the ratchet-wheel. An adjustable stop-screw 108 limits the forward thrust or movement of the said pawl, while a spring locking-dog i^8 engages the ratchet-wheel and there-

by prevents back rotation of the shaft upon which the latter is secured. A spring i^9 , suitably applied, keeps the said armature 107 normally away from the core or pole-piece of the magnet 104. This armature 107 is provided with an interrupter-arm i^{10} adapted to manipulate or operate the circuit-opening and closing springs 105 and 106; and as the construction and arrangement of these springs, and the operation of the said interrupter-arm, are identical with the construction and mode of operation of the circuit-breaker or interrupter allotted to the magnet 31, no further description of the one for the magnet 104 need be given. In Fig. 3, it will be observed that the switch-operating machine, composed of the automatic calling switch-shaft S and the automatic trunk "selector-switch-shaft" I, is mounted on a suitable support and associated with the relay 25, which latter controls one switch-point in the circuit of the "rotary-magnet" 31, and with the so-called "vertical" and "rotary" relays which control the contact-circuits of the wiper 35, only a few of such relays being shown for convenience of illustration. In Fig. 16 a detailed and amplified illustration of the construction of the "rotary-relay" 16 is shown for the purpose of more clearly bringing out the relay arrangement of the inner and outer coils, together with the normally-closed contacts controlled by such relay; and it will be understood that this construction can be employed for all of the said "vertical" and "rotary" relays.

The construction and arrangement and mode of operation of the so-called "preliminary-connectors" are as follows: Ten automatic switches of the character shown in Figs. 2 and 13, and herein termed a "preliminary-connector", may be allotted to each group of one hundred subscribers, or of eighty-one subscribers as shown in the drawings, each subscriber in any particular group being thus equipped with means for automatically selecting, out of the ten "preliminary-connectors" allotted to his group, one which is not busy, provided, of course, that the entire ten "preliminary-connectors" do not at such time happen to be busy, but which, even at a very busy hour of the day, is not likely. As shown in Fig. 13, a "preliminary-connector" is practically like an ordinary "connector", at least as far as the mechanical construction and operation is concerned, it being only necessary in a switch of this character to employ the "vertical" and "rotary" magnets 144^a and 145, and the ordinary "release-relay" and "release-magnet" k^1 and k^2 . The switch-shaft k^2 is provided with the previously described shaft-wipers 153, 154 and 155, all insulated from each other and from the said shaft. In the lower bank k^3 the "vertical" and "rotary" line-

contacts are arranged in pairs, in the well-known manner, each pair consisting, for example, of an upper contact connected by the normal 157 with the subscriber's line-conductor 1, and of a lower contact connected by the normal 158 with the subscriber's line-conductor 2; it being understood that this particular pair of contacts is, as shown, the first pair in the fifth level of the bank, and 5 is multiplied with a pair of contacts in a corresponding row in each of the other nine "preliminary-connectors". In this way, each 10 pair of contacts in this bank k^3 is connected with the normals of a subscriber's line, and 15 is multiplied with nine other pairs of contacts in the corresponding levels of the other nine "preliminary-connectors". The upper bank k^4 , however, contains only single contacts—that is to say, each level is made up 20 of ten single contacts, each of which is connected with a subscriber's bridge cut-off relay. For example, the first contact of the 25 fifth level or horizontal row of this bank k^4 is connected by the normal or conducting-wire 156 with the bridge cut-off relay 159, in the manner previously described; and it will be understood, of course, that this contact connected with the normal 156 is multiplied with nine other "private-bank-contacts" 30 in the "private-banks" of the other nine "preliminary-connectors". This shaft is also provided with the vertical ratchet-teeth k^5 , and with rotary ratchet-teeth k^6 . The "vertical-magnet" 144^a is provided with 35 an armature k^7 adapted to be pivoted at k^8 and held in its normally retracted position by a spring k^9 . At its end, the arm of this armature is provided with a pawl k^{10} , said pawl being pivoted to the arm k^{11} and subject to the tension of a spring k^{12} . When 40 the armature is attracted, the pawl k^{10} is forced into engagement with the ratchet-teeth k^5 , by any suitable guiding means, and the shaft thereby elevated one step at a time. 45 Normally, the locking-dogs k^{13} and k^{14} are out of engagement with the "vertical" and "rotary" ratchet-teeth, but are released and allowed to engage said teeth as soon as the "vertical-magnet" 144^a is energized. The 50 "release-magnet" k^1 is provided with an armature k^{15} having a horizontal arm provided at its end with an aperture k^{16} which normally engages the projection k^{17} carried by the rear end of the locking-dog member k^{18} , it being observed that the latter is adapted to be pivoted at k^{19} , and is subject to the tension of a spring k^{20} . With this arrangement, the arm k^{21} of the "release-magnet-armature" 55 is raised by the arm k^{22} when the "vertical-magnet" is energized, it being observed that this short L-shaped arm k^{22} reaches under the arm k^{21} . It is the spring k^{23} , applied to the "release-magnet-armature", which holds the two locking-dogs 60 normally out of engagement with their re-

spective ratchet-teeth. While the switch mechanism is in use for connecting purposes, the end of the arm k^{21} rests upon the upper end of the projection k^{17} , so that the locking-dogs are in engagement with the ratchet-teeth; but as soon as the "release-magnet" k^1 is energized, then the aperture k^{16} engages the projection k^{17} , and as soon as the "release-magnet" is de-energized, the spring k^{23} then jerks the armature back, and in so doing pulls the locking-dogs out of engagement with the ratchet-teeth. A supporting-dog k^{24} , adapted to engage underneath each circular vertical ratchet-tooth, supports the shaft during its rotation, and normally engages a longitudinal slot k^{25} extending vertically through the said vertical ratchet-teeth. Consequently, the shaft can only be dropped or restored to its normal position after being rotated to a position where the supporting-dog k^{24} engages the grooved slot k^{25} . The rotation of the shaft, after it has been stepped vertically to the right level, is effected by the "rotary-magnet" 145, and through the medium of the armature k^{26} and the pawl k^{27} . It will be seen that this pawl k^{27} is pivoted at k^{28} upon the arm k^{29} of the said armature, and is subject to the tension of a spring k^{30} . The armature k^{26} is held in its normally retracted position by a spring k^{31} . With this arrangement, the pawl k^{27} is forced into engagement with the ratchet-teeth k^6 when the magnet 145 is energized, this pawl being brought into and out of engagement with the teeth by means of suitable guides, in the well-known manner. At its upper end, the said shaft is provided with the usual clock-spring device k^{32} for returning it to its normal position, after it has been released by the releasing magnet. 100 The normal post arm k^{33} normally engages the spring 124, thus keeping the latter normally out of engagement with the contact 125. These contacts are closed, however, as soon as the switch starts to operate, thereby putting ground on the conductor 121 leading to the "private-bank-contacts" engaged by the "private-wiper" 101, so as to prevent seizure by any subscriber of a "preliminary-connector" which is already in use by some other subscriber. Normally, the normal post arm k^{33} is held against the normal post k^{34} by the tension of the said clock-spring device, this post acting as a stop to limit the 110 back rotation of the shaft. The "release-relay" k controls one switch-point in the circuit of the "release-magnet" k^1 , and is provided with normally open contacts k^{35} and k^{36} , the latter being grounded at k^{37} . One terminal of this "release-relay" is 115 grounded at k^{38} , while the other terminal is provided with a conductor k^{39} leading to a first "selector", or, with the arrangement shown, to the "connector-switch"; and in 120 such case, the conductor k^{39} constitutes a 125

release trunk between switches. It will be understood, of course, that a suitable framework, etc., is provided for supporting the magnets of the "preliminary-connector", and

5 for holding various operative parts in position to perform their various functions. The "private-wiper" 155 is, of course, grounded at k^{40} , while the battery 11 is grounded at k^{41} . Fig. 14 shows an ordinary "connector" 10—that is to say, a "connector-switch" having mechanism and circuits of a well-known character. It will be understood that any suitable number, say ten, of these "connector-switches" may be allotted to each group of 15 subscribers. In such case, and for each group of subscribers, there will be ten "connectors", each of which may be of the ordinary or well-known construction, and also ten "preliminary-connectors", each of which 20 comprises step-by-step mechanism of the usual or well-known character, but which in some respects, as previously described, differ from the ordinary "connector", the difference in one way being occasioned by 25 the use of a switch of this well-known general character for the purpose of connecting directly with the calling subscriber's line, rather than with the called subscriber's line, which latter has heretofore been the only 30 function, so far as I am aware, of the type of switch commonly known as a "connector". With this arrangement, therefore, each subscriber's line will terminate in the stationary or bank-contacts of ten "preliminary-connectors"—these contacts being multiplied from 35 one switch to the other—and will also terminate in the stationary or bank-contacts of ten regular or other suitable "connectors", the corresponding contacts of these "connectors" being also multiplied together from 40 one switch to another, in the manner previously explained. The arrangement, therefore, involves, for example, ten sets of contacts for each subscriber's line to be used exclusively for calls coming into the line, together with ten sets of contacts for each subscriber's line to be used exclusively for 45 out-going calls, all of said contacts being stationary; and in this way, it is not necessary for any subscriber's line to be normally connected with the wipers or brushes or other movable contacts of any other automatic switch.

50 As previously explained, the exchange, if comparatively small, may include only the "preliminary-connectors" and "connectors"; but if, on the other hand, the exchange is of considerable size, then the well-known first "selectors," second "selectors," or even third "selectors," may be included as the means for establishing connection between the "preliminary-connectors" and the regular or other suitable "connectors." All of 55 the said automatic switches, with the exception of the "preliminary-connectors", are

adapted to receive number impulses—that is to say, electrical impulses which represent the digits of a called number, as distinguished from impulses or current employed for operating other switches, or for performing other functions, preliminary to the reception by the "selectors" or "connectors" of their allotted or particular character of current; and, as previously stated, any suitable arrangement may be employed for producing such impulses or such a current-flow as will first operate the "preliminary-switches", and make the preliminary connections, before operating the "selectors" and "connectors" or other similar switches. 70 As shown, the "connector" M in Fig. 14 comprises a rotatable and vertically-movable switch-shaft m provided with a "private-wiper" m^1 , a "vertical-wiper" m^2 , and a "rotary-wiper" m^3 , it being understood that 75 these three wipers are mounted so as to move in unison with the shaft, and are insulated from the shaft and from each other. At its upper end, the said shaft is provided with the usual clock-spring device m^4 for returning it to its normal position when released. In its normal position, the normal post arm m^5 of the said shaft is held by this clock-spring device against the normal post arm m^6 . This arm, in its normal position, keeps the switch-spring m^7 out of engagement with the contact-point m^8 , these two contacts constituting the switch for closing the 80 busy signal circuit, as will hereinafter more fully appear. The said shaft is also provided with vertical ratchet-teeth m^9 , and with rotary ratchet-teeth m^{10} . Below the ratchet-drum or wheel m^{10} is the usual cam m^{11} . The locking-dogs m^{12} and m^{13} are 85 adapted respectively to engage the said rotary teeth and the said vertical teeth, but are normally out of engagement with the same, as shown in Fig. 14. The said locking-dogs are rigid with the pivoted member m^{14} , which is adapted to be pivoted at m^{15} , and which is subject to the action of a spring m^{16} tending normally to throw the 90 said dogs into engagement with their respective ratchet-teeth. This member m^{14} is provided with a projection m^{17} , and with an arm m^{18} , the latter projecting downwardly and the former upwardly. This projection m^{17} is normally engaged by an aperture m^{19} 95 in the end of a pivoted arm m^{20} , the latter being subject to the tension of a spring m^{21} and pivoted at m^{22} . When the "vertical-magnet" m^{23} is energized, it attracts its armature m^{24} , thereby raising the armature-arm m^{25} against the tension of the spring m^{26} , so as to cause the arm m^{27} to lift the latch m^{28} out of engagement with the projection m^{17} . In this way, the first impulse sent 100 through the "vertical-magnet" serves not only to force the pawl m^{28} into engagement with the vertical ratchet-teeth, but also to 105

100

105

110

115

120

125

130

release the locking-dogs. This pawl is pivoted at m^{29} to the end of the arm m^{25} , and is subject to the tension of a spring m^{30} . A supporting-dog m^{31} normally engages a channel m^{32} extending vertically through the vertical ratchet-teeth, and is adapted, when the shaft revolves, to support the same by engaging the under side of any tooth with which it happens to be in engagement. Consequently, the said shaft cannot be dropped to its normal position until after it has rotated back to a position where the dog m^{31} can engage the said channel or groove m^{32} . The armature m^{24} is adapted to be pivoted at m^{33} ; and any well-known guiding devices can be employed for directing the pawl m^{28} into and out of engagement with the teeth m^9 . The "rotary-magnet" m^{34} is provided with an armature m^{35} which is adapted to be pivoted at m^{36} . This armature is provided with an arm m^{37} having a pivotal pawl m^{38} mounted at its end. This pawl is adapted, by suitable guiding devices, to be directed into and out of engagement with the teeth m^{10} when the magnet m^{34} is alternately energized and de-energized, and is subject to the tension of a spring m^{39} . The "private-magnet" m^{40} is provided with an armature m^{41} which is adapted to be pivoted at m^{42} , and which is provided with an arm m^{43} . This arm is provided with upper and lower flat springs m^{44} and m^{45} , provided respectively with the ratchet-teeth m^{46} and m^{47} , the same pointing toward each other. A spring m^{48} keeps the armature m^{41} normally retracted, while a spring m^{49} keeps the armature m^{35} normally retracted. The arm m^{43} is provided with a laterally-projecting switch-operating-arm m^{50} carrying an insulation m^{51} at its end. This insulation is interposed between the switch-springs m^{52} and m^{53} , which are insulated from each other. The switch-springs m^{51} and m^{52} normally engage each other. The spring m^{55} is normally out of engagement with the spring m^{53} , and these springs are not closed together until the "private-magnet" is energized; and when this magnet is energized, the springs m^{52} and m^{54} are separated. The "side-switch-lever" m^{56} is adapted to be pivoted at m^{57} and is subject to the tension of a spring m^{59} , which latter tends normally to shift the "side-switch" from its normal position—that is to say, from the position in which it is normally held or locked by the innermost lower tooth m^{47} carried by the arm of the "private-magnet-armature." For this purpose, the said "side-switch" is provided with a finger m^{58} which normally engages the innermost tooth m^{47} , and which is provided with a stop-projection m^{121} . The "side-switch" is also limited in its movement by a stop m^{60} . The other end of said "side-switch-arm" is provided with a lateral projection m^{61} having a pivotal connection with

a link m^{62} , the latter being suitably connected at its end with the lower end of the previously mentioned arm m^{18} . In addition, the said "side-switch" is provided with a "vertical-wiper" m^{63} , a "rotary-side-switch-wiper" m^{64} , a "private-wiper" m^{65} , and a "magnet-switching-wiper" m^{66} ; and it will be understood that these wipers are mounted for simultaneous swinging motion from first to second position, and from second to third position, as shown in Fig. 14. For this purpose the "magnet-switching-wiper" is provided with three contacts m^{67} , m^{68} and m^{69} ; the "private-wiper" with three contacts m^{70} , m^{71} and m^{72} ; the "vertical-wiper" with three contacts m^{73} , m^{74} and m^{75} ; and the "rotary-wiper" with three contacts m^{76} , m^{77} and m^{78} . The "release-magnet" m^{79} is provided with an armature m^{80} adapted to be pivotally mounted at m^{81} . This armature is subject to the tension of a spring m^{82} tending normally to keep the armature in its retracted position. Said armature is preferably provided with an arm m^{83} adapted to engage and operate the pivoted member m^{14} carrying the locking-dogs. Obviously, when this magnet is energized, the said locking-dogs are disengaged from their respective ratchet-teeth, and the switch-shaft is, under the influence of the spring m^4 , restored to its normal position. With the arrangement shown, the "vertical" and "rotary" relay m^{84} and m^{85} are provided with armatures m^{86} and m^{87} adapted to operate the normally-separated or open contact-springs m^{88} , m^{89} , m^{90} , m^{91} and m^{92} , the latter being grounded at m^{93} . In Fig. 14, the heavy lines indicate the talking circuit—that is to say, the parallel conducting path for the voice currents; and it will be seen that these two conducting paths include the condensers m^{94} and m^{95} . As is usual in a well-known "connector-switch" of this character, the "back-release-relays" m^{96} and m^{97} are provided with armatures m^{98} and m^{99} adapted to operate the normally-open or separated springs m^{100} and m^{101} , the latter being grounded at m^{103} . The ringer-relay m^{104} is provided with an armature m^{105} adapted to operate the switch-springs m^{106} , m^{107} , m^{108} , m^{109} , m^{110} , and m^{111} . Springs m^{106} and m^{107} are normally in engagement with each other; springs m^{109} and m^{110} are normally in engagement with each other; but spring m^{108} is normally out of engagement with spring m^{107} and spring m^{111} . Spring m^{108} is normally out of engagement with spring m^{110} , so that the ringing-generator m^{112} is normally disconnected from the "vertical" and "rotary" line-conductors m^{113} and m^{114} . As shown, the "private-bank" m^{115} is adapted to be engaged by the "private-wiper" m^1 , while the "vertical" and "rotary" bank-contacts m^{116} and m^{117} are adapted to be engaged by the "vertical" and "rotary" wipers m^2 and m^3 . In the "private-bank" the con-

acts are arranged in ten horizontal rows or levels of ten single contacts each; while in the other bank there are ten horizontal rows or levels of ten pairs each, each pair consisting of a "vertical-line-contact" and a "rotary-line-contact". Each contact in the "private-bank" is connected with the bridge cut-off relay of a subscriber's line, as, for example, by means of the "private-normal" m^{118} , while the "vertical" and "rotary" line-contacts of the other bank are connected with the subscriber's line-conductor, as, for example, by means of the "line-normals" m^{119} and m^{120} . In this way, it will be seen that each subscriber's line is connected with a pair of line-contacts in each of the ten "connector-switches" allotted to the group, the different pairs of contacts allotted to a certain subscriber's line being multiplied together from one switch to the other; and in a similar way, each subscriber's bridge cut-off relay is connected with ten "private-bank-contacts" in the ten different "connector-switches". In Fig. 15, it will be seen that the normals 1^a and 2^a are adapted to extend to the "vertical" and "rotary" bank-contacts of the ten pairs of such contacts located in the ten different "connector-switches" allotted to this group of subscribers. It will also be seen that the normals 1^b and 2^b of the called subscriber's line are adapted to extend to the ten pairs of "vertical" and "rotary" contacts in the bank of the ten different "preliminary-connectors" allotted to this group of subscribers. The "private-normal" m^{156a} is adapted to extend to the ten different "private-bank contacts" in said ten different "connector-switches". The normal m^{118a} is adapted to extend to and connect with the ten different "private-bank-contacts" in the ten different "preliminary-connectors" belonging to the group of which the called subscriber is a member.

In the first "selector" N (Fig. 17) there are no "normal-conductors" leading to "connectors". Also, in this "selector" the bridge-cut-off relay is omitted, and the "line-relays" are connected directly to the battery lead. The "private-normal conductors" such as the "private-normal-conductor" of the said "selector" patent, is not needed in connection with the "selector-switch" N , and is also omitted. The "vertical-magnet" n^1 and the "rotary-magnet" n^2 and the "release-magnet" n^3 operate in the well-known manner, and the "private-magnet" n^4 , of course, controls the "side-switch-wipers" n^5 , n^6 , n^7 and n^8 , the said "private-magnet" also controlling the circuit of the "vertical-magnet" n^1 in the usual manner by means of the springs n^9 and n^{10} , but not of the "release-magnet", for the "release-magnet" spring is omitted. The vertical movement of the switch-shaft, and, therefore, of the wipers

n^{11} , n^{12} and n^{13} , is controlled by the "vertical-magnet", and the rotary movement by the "rotary-magnet", the "rotary-magnet" circuit being provided with the usual interrupter springs n^{15} . The operative magnets of the switch are, of course, controlled by the subscriber through the medium of the "vertical" and "rotary" line-relays n^{16} and n^{17} , as is well-known. Said relays have under their control the usual springs n^{18} , n^{19} and n^{20} , and in addition the trunk-release springs n^{21} and n^{22} whereby the said switch may be released when the "side-switch-wipers" are in first or second position. By means of the "back-release-relay" n^{23} the release of the switch N is brought about after the "side-switch" has passed to third position. The "selector-switch" E is of the general type of "selector-switches" disclosed in said "selector" Patent No. 815,321. The "selector" E is provided with the usual switch-shaft (not shown) which carries the line-wipers e^8 and e^4 and the "private-wiper" e^5 . The said switch-shaft is operated by the "vertical" and "rotary" magnets e^6 and e^7 , which are in turn controlled by the "vertical" and "rotary" line-relays e^8 and e^9 . The "side-switch", comprising the "side-switch-wipers" e^{10} , e^{11} , e^{12} and e^{13} , is under the control of the "private-magnet" e^{14} . The "release-magnet" e^2 provides the means of restoring the switch to normal position after it has operated. Since the "selector" E is of the trunk-release type, the "release-magnet" e^2 is controlled by the "back-release-relay" e^1 , after the "side-switch" passes to third position. The third "selector" O is also a modified form of the "selector-switch" disclosed in said "selector" patent, and comprises the "vertical-magnet" o^1 , "rotary-magnet" o^2 , "release-magnet" o^3 and the "private-magnet" o^4 , which latter, of course, controls the "side-switch-wipers" o^5 , o^6 , o^7 and o^8 , the said "private-magnet" also controlling the circuit of the "vertical-magnet" o^1 , in the usual manner, by means of the springs o^9 and o^{10} but not of the "release-magnet", for the "release-magnet" springs are omitted. The vertical movement of the switch-shaft (not shown), and therefore of the "line-wipers" o^{11} and o^{12} and the "private-wiper" o^{13} , is controlled by the "vertical-magnet", and the rotary movement by the "rotary-magnet", the "rotary-magnet" being provided with the usual interrupter springs o^{14} . The operative magnets of the switch are, of course, controlled by the subscriber through the medium of the "vertical" and "rotary" line-relays o^{15} and o^{16} , as is well-known. In addition to the usual springs these relays control the trunk-release springs o^{17} and o^{18} , whereby the said switch may be released when the "side-switch" is in first or second position. By means of the "back-

release-relay" σ^{19} the release of the switch O is brought about after the "side-switch" passes to third position.

Referring to Fig. 12, which shows the calling subscriber's apparatus, it will be seen that the bell a^{25} is normally bridged across the subscriber's line through the medium of the contacts a^{26} and a^{27} , the body of the switch-hook a , and the conductors a^4 and a^{28} ; but this bridge is broken, of course, as soon as the receiver is removed from the hook. The arrangement is preferably such that a^1 makes and breaks contact with a^2 before a^{14} and a^{15} are closed together, and after a^{27} breaks contact with a^{26} ; and while this arrangement and mode of operation will give the desired results, it is obvious that any other suitable switching arrangement may be employed, consistent with the mode of operation of the switch-operating machine and other switches. When the switch-hook moves upwardly, the projection a^{21} passes between the springs a^{22} and a^{23} , so that these three springs are not brought together. However, when the receiver is replaced upon the hook, then the projection a^{21} engages the outside of the contact a^{22} , thus closing all three of the springs together in the manner described. The contacts a^6 and a^7 are normally separated, and only brought together by the lifting of the hook-switch-arm a^{29} . The other hook-switch-arm a^{30} is adapted to close together the normally-separated contacts a^{14} and a^{15} included in the circuit of the conductor l and the push-button-arm a^{12} . When the switch-hook is depressed, by the replacing of the receiver, the projection a^1 engages the outside of the contact a^2 , but does not make electrical connection therewith owing to the provision of the insulation a^{34} .

From the foregoing it will be seen that, with my improved arrangement, only one switch-operating machine is necessary for each group of subscribers; that only the "line-relays", together with the bridge cut-off relays, are individual to the different lines; that the automatic switches employed are less in number than the total number of subscribers, and that for each group of one hundred subscribers, for example, only ten "preliminary-connectors" and ten ordinary or other suitable "connectors" are necessary to an efficient and perfectly satisfactory operation of the system; and that efficient telephone service is thus provided between subscribers by means of apparatus involving a material and substantial reduction in the number of switches required for permitting any particular subscriber to communicate with any other subscriber at practically any and all times except when the called subscriber's line is actually in use or busy for other purposes.

It will be seen that the switch-operating

machine illustrated diagrammatically in Fig. 1 comprises two mechanisms one a numerical impulse-transmitter for transmitting the electrical impulses corresponding to the number of the calling subscriber's line, and the other a trunk selector provided with means for distinguishing between busy and idle trunks, combined with automatic means by which such selector maintains all idle subscribers' lines or telephone lines in selective relation to the first idle trunk-line next in order after the one last in use. With this arrangement the numerical impulse-transmitter is normally in electrical connection with the first idle trunk-connecting switch K next in order after the switch last put in use. It will be understood, of course, that the said switch last put in use may have been restored, but that regardless of whether it has been restored or is still in use the normal connection from the numerical impulse-transmitter is with the first idle trunk-connecting switch next in order after the one last in use. Consequently, the subscribers' lines or telephone lines—that is, all idle lines—are normally maintained in selective relation to the first idle trunk-line next in order after the one last in use. With such arrangement and method of operation, each calling subscriber gets a pre-selected trunk-line, and at the same time selects the next idle trunk-line for the next call. In this way, each calling subscriber does not make a selection for himself, but to the contrary makes a selection for the subscriber who makes the next call, or, of course, if the same subscriber should call twice he would then, and by the second call, obtain connection with the trunk-line which he had automatically selected when he made his first call. It will be seen that in a small sized exchange, such as shown, each subscriber's number only includes two digits, namely the tens and the units digits of such number. Should the exchange be enlarged, however, so as to make necessary or desirable the employment of numbers containing four digits, it is evident that the numerical impulse-transmitter of the switch-operating machine would then only call the last two digits of each calling subscriber's number. In other words, with the exchange thus enlarged each subscriber would have a four digit number, and the last two digits of each number would constitute the group number, so to speak, of each subscriber. For example, if in an exchange thus enlarged to give service to a greater number of subscribers a certain subscriber's number should be 5566, such number would then be the exchange number of that particular subscriber, and the last two digits (66) would constitute such subscriber's group number—that is to say, would constitute his number in the particular group in which his sub-station was in-

cluded. In this connection it will be understood, of course, that all this may result from the simple arrangement of the system in groups of one hundred subscribers for each group, thus making it possible to give each subscriber an exchange number composed of any suitable number of digits, and a group number composed of only two digits, namely the last two digits of the general or exchange number. The switch-operating machine will have as many sets of cut-out-relays—such as the relays 16, 165, 166, etc.—as there are digits in the group numbers of the group of subscribers to whom such switching machine is allotted. Each set of cut-out-relays has a corresponding set of contacts on the numerical impulse-transmitter, and each set of cut-out-relays is adapted to cut out one or more of its allotted set of contacts, according to the number of electrical impulses necessary to represent each digit of the calling subscriber's number. In other words, the numerical impulse-transmitter will transmit as many distinct and separate groups of impulses as there are digits in the calling subscriber's number, and the number of impulses in each group will depend upon the number of contacts which are not cut out of the different sets of contacts by the automatic action of the cut-out-relays. Thus each calling subscriber not only uses his individual line-relay means, but also uses one relay in each of the different sets of cut-out-relays, substantially in the manner shown and described. With the arrangement shown the entire trunk-selecting and connecting apparatus is normally at rest. The switch-operating machine is normally at rest and does not have any motion or movement until some subscriber makes a call.

It will be seen that each trunk connector or preselector K represents a group of subscribers, and that each level in the bank of line contacts thereof represents a sub-group. For raising the wipers to the level of any sub-group, there are as many local circuits as there are levels or sub-groups (see Fig. 1), so that the said wipers can be raised to any level.

What I claim as my invention is:—

1. A normally at rest switching apparatus comprising a plurality of switches, each provided with step-by-step propelling mechanism, and a switch-operating device common to all of said switches, together with automatic means for electrically connecting the said device with and disconnecting it from the said step-by-step mechanism, said device normally connected with one of said switches, whereby said device may be used for operating any one of said switches without interfering with its subsequent use for operating other switches while the said operated switch remains in use.

2. A normally at rest switching apparatus comprising a plurality of switches, each provided with electro-magnetically-actuated propelling means, and a switch-operating machine common to all of said switches, said machine including automatic means for opening and closing electrical connection with the said propelling means of the different switches, one at a time whereby said machine may be employed for operating any switch without interfering with its subsequent use for operating other switches while the said operated switch remains in use.

3. A switching apparatus comprising telephone lines, a plurality of switches, each provided with electro-magnetically-actuated operating means, and electro-magnetically actuated electrical-impulse-transmitting means for operating said switches, individual line-relays for starting the operation of said impulse-transmitting means, and automatic means for electrically connecting the said impulse-transmitting means with the said operating means of any switch, and for disconnecting it therefrom, whereby said impulse-transmitting means may be employed for operating any switch without interfering with its subsequent use in operating other switches while the said operated switch remains in use.

4. A normally at rest switching apparatus comprising an automatic two-motion switch having electro-magnetically-actuated operating means, and automatic electro-magnetically-actuated electrical-impulse-transmitting means suitably connected and controlled for operating said switch, said transmitting means adapted to call the number of the calling subscriber, and said automatic switch adapted to respond by finding the calling subscriber's line.

5. An automatic telephone system comprising a calling subscriber's line, an automatic step-by-step two-motion switching device, a switch-operating machine, and centrally located individual means under the control of the subscriber for causing said machine to automatically call the number of the calling subscriber, and thereby causing said switch to close a connection to the calling subscriber's line.

6. An automatic telephone system comprising a calling subscriber's line, and automatic means having vertical and rotary motions at the central station, but under the control of the said subscriber, for automatically calling and connecting with his own substation preliminary to calling the other subscriber.

7. An automatic telephone system comprising a calling subscriber's line, means having vertical and rotary motions under the control of the subscriber for calling any other subscriber, and automatic impulse transmitting means at the central station,

but under the control of the calling subscriber, for automatically calling his own substation preliminary to or just before calling the number of some other subscriber.

5. 8. An automatic telephone system comprising a plurality of subscribers' lines, a plurality of switches less in number than the total number of said subscribers, trunk-lines leading from said switches, and a normally 65
10 at rest switch-operating machine common to all of said switches and under the control of the subscribers, whereby any one of said subscribers may cause one of said switches to connect one of said trunk-lines with his line 70
15 before calling the number of any other subscriber.

9. An automatic telephone system comprising a group of subscribers' lines, a plurality of automatic two-motion switches 75
20 common to all of said lines but less in number than the latter, trunk-lines for talking purposes leading from said switches, normally at rest means under the control of the subscribers for operating said switches, 80
25 whereby a calling subscriber may cause one of said switches to connect a trunk-line with his line preliminary to calling the number of another subscriber.

10. An automatic telephone system comprising a group of subscribers' lines, a plurality of switches common to said lines, but less in number than the latter, trunk-lines leading from said switches, other switches in which the said trunk-lines terminate, 85
30 and a normally at rest switch-operating machine common to all of said first-mentioned switches, together with individual relay means under the control of the subscribers for causing said machine to operate said first-mentioned switches, whereby the calling subscriber may connect his line with one of said trunk-lines before operating one of said other switches in accordance with the first digit of the called number. 90
40
45

11. An automatic telephone system comprising a group of subscribers' lines, a plurality of switches allotted to and common to all of said lines, but less in number than the latter, other switches suitably connected with said first-mentioned switches, together with manually-controlled normally at rest means by which any subscriber may cause one of said first-mentioned switches to connect his line with one of said other switches preliminary to operating the latter in accordance with the first digit of the called number. 100
50
55

12. An automatic telephone system comprising a group of subscribers' telephone lines, a plurality of step-by-step trunk-connecting switches allotted to and common to all of said lines, but less in number than the latter, other step-by-step switches, and man- 105
60

ually-controlled normally at rest means by which any calling subscriber in said group may connect his line with one of said other switches preliminary to causing one of said other switches to begin operating in accordance with the first digit of the called number. 110
70

13. An automatic telephone system comprising a group of subscribers' telephone lines, individual line-relays, a plurality of two-motion step-by-step switches allotted to and common to all of said lines, but less in number than the latter, each line terminating in stationary multiple switch-contacts of all of said switches, said contacts being adapted for use in making only out-going calls from said lines and means for including said contacts in talking circuits. 115
75
80

14. An automatic telephone system comprising a group of subscribers' telephone lines, individual line-relays, a plurality of two-motion switches common to all of said lines, but less in number than the latter, and means under the control of the relays for operating said switches, each switch having stationary multiple switch-contacts connected with all of said subscribers' lines, said contacts being arranged in banks and adapted for transmitting voice currents in both directions, but adapted for use only in making out-going calls from said lines. 120
85
90

15. An automatic telephone system comprising a plurality of subscribers' telephone lines, individual lines-relays, a plurality of automatic switches common to all of said lines, but less in number than the latter, each line being connected with stationary multiple switch-contacts of all of said switches, said contacts being adapted for use in making only out-going calls from said lines, another group of automatic switches common to all of said lines for one subscriber calling another in the group, but less in number than the latter, said lines being also connected with stationary multiple switch-contacts in all of said last-mentioned switches, but said last-mentioned contacts being adapted for use in making only incoming calls to said lines. 125
100
105
110

16. The combination of a subscriber's line, a step-by step switching device, a normally at rest switch-operating machine electrically connected for operating said step-by-step switching device, and means under the control of the subscriber for causing said machine to operate said switching device. 130
115
120

17. An automatic telephone system comprising a plurality of subscribers' telephone lines, a plurality of automatic two-motion switches common to all of said lines, but less in number than the latter, and normally at rest automatic means under the control of the subscribers, for automatically selecting and operating an idle one of said switches 135
125

and means for extending a connection in accordance with the number of the called line.

18. An automatic telephone system comprising a plurality of subscribers' telephone lines, individual line-relays, subscribers' switching apparatus adapted for transmitting electrical impulses over the lines, according to the character and number of digits in any called number, and a plurality of automatic switches common to all of said lines, but less in number than the latter, each subscriber's apparatus being adapted for setting up a current-flow sufficient to cause the operation of one of said switches preliminary to the transmission of the current-flow to be employed exclusively in calling the number of the called subscriber.

19. An automatic telephone system comprising a plurality of subscribers' telephone lines, a "line-relay" normally in bridge in each line at the central station, a bridge cut-off relay for each line, a plurality of switches common to all of said lines, but less in number than the latter, a machine having a plurality of normally-open circuits controlled by said "line-relays", automatic means for insuring the connection of an idle switch with the said machine when a subscriber calls in, means for setting said machine in operation whenever a subscriber attempts to communicate with another subscriber, the circuits controlled by each subscriber's "line-relay" being of such character and combined with operative means of such nature that the said machine, when set in operation, will always transmit to the idle switch a call corresponding to the number of the calling subscriber, together with means whereby each idle switch, upon closing a connection to a calling subscriber's line, effects the energizing of the bridge cut-off relay belonging to such line.

20. An automatic telephone system comprising subscriber's telephone lines, individual line-relays, a group of automatic switches common to all of said lines, but less in number than the latter, each switch having a pair of stationary contacts for each subscriber's line, corresponding contacts of different switches being multiplied together, another set of automatic switches common to all of said lines for one subscriber calling another in the group, but less in number than the latter, these last-named switches being also each provided with a pair of stationary contacts for each line, corresponding contacts of the different last-named switches being multiplied together, and two pairs of "line-normals" for each line, one pair connected to all of the multiple-contacts belonging to such line in one set of switches, and the other pair of "line-normals" connected to all of the multiple-

contacts belonging to such line in the other set of switches.

21. A telephone system comprising a plurality of subscribers' telephone lines, individual line relays, a plurality of trunk-lines for talking purposes common to all of said subscriber's lines for one subscriber calling another in the group, but less in number than the latter, a plurality of automatic switches also common to all of said subscribers' lines, but less in number than the latter, and each adapted for establishing connection directly to any calling subscriber's line from one of said trunk-lines.

22. An automatic telephone system comprising subscribers' telephone lines, a plurality of "preliminary-connectors" common to all of said lines, but less in number than the latter, a "line-relay" normally in bridge of each line, a bridge cut-off relay for each line, a plurality of "connectors" common to said lines, but less in number than the latter, and means under the control of the subscribers for effecting the operation of said "preliminary-connectors", and also of said "connectors", each "preliminary-connector" being adapted, upon establishing connection with a calling subscriber's line, to energize the bridge cut-off relay of such line, and also establish a guarding potential at all of the "connectors" having connection with such line.

23. In a telephone system, a calling line, an automatic switch associated with said line, means controlled from said line for operating the switch to cause it to call the number of the calling line, including a series of contacts, a movable element for said switch associated with said contacts, said operating means all being normally at rest and said element being always movable in the same direction.

24. In a telephone system, a calling line, an automatic switch associated with said line, means controlled from said line for operating the switch to cause it to call the number of the calling line, including a series of contacts, a movable element for said switch associated with said contacts, said operating means all being normally at rest and said element being always movable in the same direction, said means comprising a plurality of circuits controlled by relays.

25. In a telephone system, a calling line, an automatic switch associated with said line, means controlled from said line for operating the switch, including a series of contacts, a double ended wiper for said switch having its opposite ends adapted to alternately engage said contacts, said operating means all being normally at rest and said element being always movable in the same direction.

26. In a telephone system, a calling line,

an automatic switch associated with said line, means controlled from said line for operating the switch, including a series of contacts, a movable element for said switch 5 associated with said contacts, said operating means all being normally at rest and comprising a shaft, a ratchet wheel on said shaft, a pawl for controlling said ratchet wheel and an electromagnet for retracting 10 the pawl and a spring for advancing the same, and said element being always movable in the same direction.

27. An automatic telephone system comprising a bank of contacts, a suitably propelled wiper adapted to travel around upon said contacts, a couple of conducting paths containing a plurality of normally-closed switch-points, conductors connecting said contacts with said conducting paths, each of 15 said switch-points being located intermediate of the two points at which two adjacent contacts are connected with the conducting path containing such switch-point, two sets of relays for controlling said two sets of 20 switch-points, means under the control of the calling subscriber for operating one relay in each set in accordance with the number of the calling subscriber, and a step-by-step switching device provided with 25 wipers or movable switching-arms connected with said conducting paths, together with a plurality of step-by-step switches connected with said step-by-step switching device and adapted to be operated by the impulses 30 transmitted by the rotation of the said first-mentioned wiper.

28. An automatic telephone system comprising a plurality of "vertical-line-relays," a plurality of "rotary-line-relays," a plurality 40 of subscribers' lines, a "line-relay" for each line, circuits for said "vertical" and "rotary" relays controlled by said "line-relays," each "line-relay" controlling the circuit of one "vertical-relay" and one "rotary-relay," according to the number of the 45 subscriber to whom such "line-relay" is allotted, a plurality of circuits controlled by said "vertical" and "rotary" relays, and automatic means for transmitting impulses 50 through said last-mentioned circuits, the number of impulses transmitted each time depending upon which, if any, of said last-mentioned circuits have been opened by the energizing of any particular calling subscriber's line-relay.

29. A telephone system comprising a group of telephone lines, a plurality of switches less in number than said lines, provided with stationary banks of multiple 60 terminals for said lines, a trunk-line leading from each switch, and a machine for operating said switches, adapted for use only by calling subscribers in preliminarily and automatically operating said switches, to 65 close connection between calling telephone

lines and idle trunk-lines, provided with automatic means for skipping busy switches and stopping in operative connection with the first idle switch, said machine provided also with electrical impulse-transmitting 70 means for calling the number of the calling subscriber, to cause the selected switch to connect its trunk-line with the calling telephone line, said switches each having a set of swinging wipers connected with its 75 allotted trunk-line and adapted to co-operate with its bank of terminals in connecting the same with any of said telephone lines.

30. A telephone system comprising trunks, telephone lines to be connected with said trunks, switching means for so doing, a trunk-selecting mechanism, an electrical impulse-transmitting mechanism associated with said selecting mechanism, and subscriber-controlled automatic means for causing the impulses received by said switching means from said transmitting mechanism to always correspond to the number of the calling telephone line, said switching means provided with means for causing said selecting 80 mechanism to select the next idle trunk-line each time the previously selected trunk-line is put in connection with a calling telephone line, whereby each calling subscriber always gets the idle trunk-line automatically 85 selected by the previous call.

31. A telephone system comprising a group of trunks, a trunk-selecting and connecting apparatus, substation means for controlling said apparatus, and telephone lines 90 connecting the said apparatus with the substations, said apparatus provided with means for distinguishing between busy and idle trunks, adapted to skip busy trunks and stop on the first idle trunk, and provided also with automatic means by which connection with a selected trunk compels selection of the next idle trunk, whereby each calling subscriber always gets the idle trunk next 95 in order after the one last put in use, and selects a trunk for the next subscriber.

32. In a telephone system, the combination of trunks, means for automatically calling the number of a calling subscriber, and means by which said calling subscriber automatically selects a trunk for the next call.

33. A telephone system provided with trunks, and automatic trunk-selecting and connecting apparatus by which each calling subscriber selects a trunk for the next call.

34. A telephone system comprising a group of telephone lines, trunks less in number than said lines, said lines all normally in selective relation to the idle trunk next in order after the one last put in use, and automatic means by which each calling line takes the waiting trunk and selects another for the next call.

35. A telephone system comprising a number-calling device provided with a plurality 130

of contacts, a wiper adapted to move over said contacts, and cut-out-relays each adapted to cut out one or more of said contacts, according to the number to be called.

5 36. A telephone system comprising an automatic number-calling mechanism provided with a plurality of groups of cut-out-relays one group for each digit of the number to be called, and a set of contacts for each 10 group, each relay adapted to cut out one or more of the contacts of the set allotted to the group to which it belongs.

37. In a telephone system, the combination of telephone lines, a set of switches for 15 use only in connecting directly with a calling line, preliminary to making connections in accordance with the called number, automatic means for maintaining all idle lines in selective relation to the first idle switch 20 next in order after the switch last in use, automatic means for operating any selected switch in accordance with the number of the calling line, and individual-line-relays controlling said automatic means, whereby 25 each calling subscriber selects a switch for the next call.

38. In a telephone system, the combination of automatic means for calling the number of the calling subscriber, a suitable number 30 of telephone lines, a number of trunk connections common to said lines, and automatic means for maintaining all idle lines in selective relation to the first idle trunk connection next in order after the one last 35 in use, whereby each calling subscriber gets a pre-selected trunk connection.

39. In a telephone system, the combination of trunk-lines, automatic mechanism by 40 which each calling subscriber selects a trunk-line for the next call, and automatic means by which each calling subscriber simply closes connection with the pre-selected or waiting trunk-line.

40. In a telephone system, means for automatically calling the number of the calling line each time a subscriber starts to make 45 a call, located at the central station or exchange, comprising means for transmitting separate and distinct groups of electrical impulses for and corresponding to each digit 50 of the said number, means operated by said impulses, adapted to select and connect with the calling line, and subscribers' individual line-relays for controlling said impulse-transmitting means.

41. In a telephone system, the combination 60 of individual line-relays, a line for each relay, said lines arranged in a group, automatic means at the central station for calling the group number of any calling line, controlled by said relays and suitable means having motion in two directions for connecting in accordance with the number thus called.

65 42. In a telephone system, the combination

of a plurality of switches, trunk-lines leading from said switches, telephone lines, automatic trunk-selecting mechanism adapted to distinguish between idle and busy trunk-lines, automatic means by which said selecting mechanism maintains all idle telephone lines in selective relation to the first idle trunk-line next in order after the one last in use, and a switch-operating mechanism common to all of said switches, adapted for 70 use by calling subscribers in operating said switches.

43. In a telephone system, the combination of a plurality of switches, trunk-lines leading from said switches, telephone lines, 75 automatic trunk-selecting mechanism adapted to distinguish between idle and busy trunk-lines, automatic means by which said selecting mechanism maintains all idle telephone lines in selective relation to the first 80 idle trunk-line next in order after the one last in use, a switch-operating mechanism common to all of said switches, adapted for use by calling subscribers in operating said switches, and individual line-relays for said 85 telephone lines.

44. In a telephone system, the combination of a plurality of switches, trunk-lines leading from said switches, telephone lines, 90 automatic trunk-selecting mechanism adapted to distinguish between idle and busy trunk-lines, automatic means by which said selecting mechanism maintains all idle telephone lines in selective relation to the first 95 idle trunk-line next in order after the one last in use, a switch-operating mechanism common to all of said switches, adapted for use by calling subscribers in operating said switches, each said switch provided with a multiple terminal of each of said telephone 100 lines.

45. In a telephone system, the combination of a plurality of switches, trunk-lines leading from said switches, telephone lines, 105 automatic trunk-selecting mechanism adapted to distinguish between idle and busy trunk-lines, automatic means by which said selecting mechanism maintains all idle telephone lines in selective relation to the first 110 idle trunk-line next in order after the one last in use, a switch-operating mechanism common to all of said switches, adapted for use by calling subscribers in operating said switches, each said switch having a rotatable and vertically-movable switch-shaft, wipers on said shaft, and a bank of line-terminals 115 for said wipers.

46. In a telephone system, the combination of a switching machine provided with 120 a bank of line-terminals, lines leading to said terminals, a trunk-line for talking purposes leading from said machine, a trunk for switching purposes leading to said machine, and means for transmitting numerical impulses over said trunk to cause said ma- 125

chine to connect said trunk-line with one of said line-terminals.

47. In a telephone system, the combination of a switching machine provided with 5 a bank of line-terminals, lines leading to said terminals, a trunk-line leading from said machine, a trunk leading to said machine, means for transmitting numerical impulses over said trunk to cause said machine 10 to connect said trunk-line with one of said line-terminals, and individual line-relays for the lines leading to said machine.

48. In a telephone system, the combination of trunks, an automatic numerical impulse- 15 transmitter, an automatic trunk-selecting mechanism provided with means for distinguishing between busy and idle trunks, and automatic means for maintaining said transmitter in connection with the first idle 20 trunk next in order after the one last in use.

49. In a telephone system, an automatic electrical impulse-transmitter provided with a wiper for making a complete revolution each time any subscriber calls, means by 25 which calling subscribers initiate the operation of said transmitter, automatic means for varying the number of impulses for different calling subscribers, and means responsive to said impulses for finding the 30 calling subscribers.

50. In a telephone system, an automatic electrical impulse-transmitter provided with a wiper for making a complete stroke or maximum movement each time any subscriber calls, means by which calling subscribers 35 initiate the operation of said transmitter, automatic means for varying the number of impulses for different calling subscribers, and means responsive to said impulses for finding the calling subscribers. 40

51. In a telephone system, an automatic electrical impulse-transmitter having the same range of movement or operation each time any subscriber calls, means by which 45 calling subscribers initiate the operation of said transmitter, automatic means for varying the number of impulses for different calling subscribers, and means responsive to said impulses for finding the calling subscribers. 50

52. In a telephone system, an automatic electrical impulse-transmitter provided with a series of contacts, a wiper for engaging said contacts, means for moving the wiper 55 over all of the contacts each time any subscriber calls, means for automatically cutting out one or more of said contacts to vary the number of impulses for the different subscribers, means by which calling subscribers 60 initiate the operation of said transmitter, and means responsive to said impulses for finding the calling subscribers.

53. In a telephone system, an automatic electrical impulse-transmitter provided with 65 a series of contacts, a wiper for engaging

said contacts, a series of relays for moving the wiper over all of the contacts each time any subscriber calls, means for automatically cutting out one or more of said contacts to vary the number of impulses for the different 70 subscribers, means by which calling subscribers initiate the operation of said transmitter, and means responsive to said impulses for finding the calling subscribers.

54. In an automatic telephone system, the combination, with the subscribers' lines divided in groups, of a plurality of preselectors and first-selectors for each line group, each preselector comprising line contacts connected to the subscribers' lines of the group, a traveling contact device and means for moving said contact device to cause it to make contact with the line contacts, each first-selector comprising line contacts, a traveling contact device in electrical communication with the traveling contact device of one of the preselectors, and means for moving this traveling contact to its line contacts, trunk lines connected in multiple to the line contacts of the first-selectors, an auxiliary switch common to a plurality of preselectors, coupled for a call with one of said preselectors and working simultaneously with the same, and means connected with the trunk lines and arranged to make 85 the final connection over the selected trunk line to the desired subscriber.

55. In a automatic telephone system, the combination, with the subscribers' lines divided in groups, of a plurality of preselectors for each line group, each comprising line contacts connected in multiple to the respective subscribers' lines of the group, a traveling contact device and means for moving said contact device to cause it to make 100 contact with the line contacts, a plurality of first-selectors for each line group, each having line contacts, trunk lines divided in sets and connected in multiple to the line contacts of the first-selectors, a traveling contact device for each first-selector, the traveling contact device of each first-selector being in electrical communication with the traveling contact device of one of the preselectors, an auxiliary switch common to a plurality 105 of preselectors, coupled for a call with one of said preselectors and working simultaneously with the same, means for moving the traveling contact device of each first-selector into engagement with the contacts of an unoccupied trunk line of the desired set, and means connected with the contacts of the first-selectors and arranged to make the final 110 connections to the desired subscriber.

56. In an automatic telephone system, the combination, with the subscribers' lines divided in groups, and for each line group a plurality of pairs of switches, each pair comprising a preselector and a first-selector, each preselector and first-selector compris- 115 120 125 130

- ing line contacts, a traveling contact device coating with the individual line contacts and means for moving the traveling contact device, the traveling contact device of each 5 preselector being in electrical communication with the traveling contact device of its companion first-selector, an auxiliary switch common to a plurality of preselectors, coupled for a call with one of said preselectors 10 and working simultaneously with the same, the line contacts of the preselectors being connected to the respective subscribers' lines of the group, of trunk lines divided in sets and connected in multiple to the line contacts of the first-selectors, and means arranged to make the final connection to the desired subscriber.
57. In an automatic telephone system, the combination, with the subscribers' lines divided in groups, of a plurality of pairs of 20 switches for each line group, each pair comprising a preselector and a corresponding first-selector, each preselector and first-selector comprising line contacts, a traveling contact device and means for moving the traveling contact device into engagement with the single line contacts, the traveling contact device of each preselector being in electrical communication with that of its 25 companion first-selector, the line contacts of the preselectors being connected to the corresponding subscribers' lines, trunk lines connected to the line contacts of the first-selectors, an auxiliary switch common to a plurality of 30 preselectors, coupled for a call with one of said preselectors and working simultaneously with the same, a calling relay for each subscriber arranged to set in action said auxiliary switch and the means for moving the traveling contact device of an idle preselector, and to stop the said preselector 35 upon the arrival of its traveling contact device at the contacts of the calling subscriber's line, and means at the calling station for controlling the traveling contact device of the corresponding first-selector.
58. In an automatic telephone system, the combination, with the subscribers' lines divided in groups, a plurality of preselectors and first-selectors for each line group arranged in pairs, each preselector and first- 40 selector comprising line contacts, a traveling contact device and means for moving its traveling contact device, the traveling contact device of each preselector being in electrical communication with that of its corresponding first-selector, the subscribers' lines 45 of the group being connected to the line contacts of the preselectors, trunk lines connected to the line contacts of the first-selectors, an auxiliary switch common to a plurality 50 of preselectors, coupled for a call with one of said preselectors and working simultaneously with the same, a calling relay for each subscriber's line arranged to set in action said auxiliary switch and an idle preselector 55 tor upon a call, means at the subscribers' 60 stations to actuate automatically the corresponding calling relay when the receiver is taken up, and means at the subscribers' stations for operating and controlling the first-selector and for making the final connection 65 over the selected trunk line.
59. In an automatic telephone system, the combination, with the subscribers' lines divided in groups, of a plurality of pairs of switches for each line group, each pair comprising a preselector and corresponding first-selector, each preselector and first-selector comprising line contacts, a traveling contact device and means for moving the traveling contact device into engagement with the single line contacts, the traveling contact device of each preselector being in electrical communication with that of its companion first-selector, the line contacts of the preselector being connected to the corresponding subscribers' lines, trunk lines connected to the line contacts of the first-selectors, an auxiliary switch common to a plurality of 70 preselectors, coupled for a call with one of said preselectors and working simultaneously with the same, a calling relay for each subscriber arranged to set in action said auxiliary switch and the means for moving the traveling contact device of an idle preselector, and to stop the said preselector 75 upon the arrival of its traveling contact device at the contacts of the calling subscriber's line, and means at the calling station for controlling the traveling contact device of the corresponding first-selector.
60. In an automatic telephone system, the combination, with the subscribers' lines divided in groups, of a plurality of pairs of switches for each line group, each pair comprising a preselector and a corresponding first-selector, each preselector and first-selector comprising line contacts, a traveling contact device and means for moving the traveling contact device into engagement with the single line contacts, the traveling contact device of each preselector being in electrical communication with that of its companion first-selector, the line contacts of the preselectors being connected to the corresponding subscribers' lines, trunk lines connected to the line contacts of the first-selectors, an auxiliary switch common to a plurality of preselectors, coupled for a call with one of said preselectors and working simultaneously with the same, a calling relay for each subscriber, a common calling relay arranged to be actuated by any subscriber's calling relay and to set in action said auxiliary switch and the means for moving the traveling contact device of an idle preselector, and means actuated at the calling station for operating the traveling contact device of the corresponding first-selector.
61. In an automatic telephone system, the 130

combination, with the subscribers' lines divided in groups, of a plurality of switches for each line group, said switches being arranged in pairs, each pair comprising a pre-
 5 selector and a first-selector, each preselector and its first-selector comprising line contacts, a traveling contact device arranged to engage said line contacts, the traveling contact device of each preselector being in
 10 electrical communication with that of the corresponding first-selector, the line contacts of each preselector being connected to the corresponding subscribers' lines, trunk lines connected to the line contacts of the first-
 15 selector, means for moving said traveling contact devices, an auxiliary switch common to a plurality of preselectors, coupled for a call with one of said preselectors and working simultaneously with the same, a calling
 20 relay for each subscriber arranged to set in action the means for moving the traveling contact device of a preselector, a cut-off relay for each subscriber arranged to cut out the calling subscriber's calling relay when
 25 the preselector is set on the calling line, means at the calling station for controlling the traveling contact device of the first-selector, and means operated over the selected trunk line for making the final con-
 30 nection to the desired subscriber.

62. In an automatic telephone system, the combination, with the subscribers' lines divided in groups, of a plurality of switches for each line group, said switches being arranged in pairs, each pair comprising a pre-
 35 selector and a corresponding first-selector, each preselector and its first-selector comprising line contacts, a traveling contact device arranged to engage said line contacts, the traveling contact device of each preselector being in electrical communication with that of the corresponding first-selector, the line contacts of each preselector being connected to the corresponding subscribers' lines, trunk lines connected to the line contacts of the first-selectors, an auxiliary switch common to a plurality of preselectors, coupled for a call with one of said preselectors and working simultaneously with the same, means for moving said traveling contact devices, a calling relay for each subscriber arranged to set in action said auxiliary switch and the means for moving the traveling contact device of a preselector, a cut-off relay for each subscriber arranged to cut out the called subscriber's calling relay, means actuated at the calling station for controlling the traveling contact device of the first-selector, and means operated over the selected trunk line for making the final connection to the desired subscriber.

63. In an automatic telephone system, the combination, with the subscribers' lines divided in groups, of a plurality of switches for each line group, said switches being ar-

ranged in pairs, each pair comprising a pre-
 selector and a first-selector, each preselector and its first-selector comprising line contacts, a traveling contact device of each preselector being in electrical communication with that of the corresponding first-selector, the line contacts of each preselector being connected to the corresponding subscribers' lines, trunk lines connected to the line contacts of the first-selectors, means for moving said traveling contact devices, an auxiliary switch common to a plurality of preselectors, coupled for a call with one of said preselectors and working simultaneously with the same, and a pair of relays for each subscriber's line, each pair comprising a calling and a cut-off relay, the calling relay being arranged to set in action said auxiliary switch and an idle preselector upon a call, the cut-off relay being arranged to cut out its calling relay when the corresponding subscriber's line is occupied.

64. In an automatic telephone system, the combination, with the subscribers' lines divided in groups, of a plurality of preselectors and first-selectors for each line group, each comprising line contacts, a traveling contact device arranged to engage its line contacts, and means for moving the traveling contact device, the traveling contact device of each preselector being in electrical communication with that of one of the first-selectors, the contacts of the preselectors being connected to the corresponding subscribers' lines, trunk lines connected in multiple to the first-selectors, an auxiliary switch common to a plurality of preselectors, coupled for a call with one of said preselectors, and arranged to control its traveling contact device to bring the same as needed in engagement with the contacts of a calling line, means actuated at the calling station for moving the traveling contact device of the first-selector and for making the final connection over the selected trunk line to the desired subscriber.

65. In an automatic telephone system, the combination, with the subscribers' line divided in groups, of a plurality of preselectors and first-selectors for each line group, each comprising line contacts, a traveling contact device arranged to engage its line contacts, and means for moving the traveling contact device, the traveling contact device of each preselector being in electrical communication with that of one of the first-selectors, the contacts of the preselectors being connected to the corresponding subscribers' lines, trunk lines connected in multiple to the first-selectors, an auxiliary switch common to a plurality of preselectors, coupled for a call with one of said preselectors and arranged to drive its traveling contact device to the contacts of the calling subscriber's line, a preselector finder controlled by

the preselectors and arranged to couple an idle preselector for the next call with said auxiliary switch, means actuated at the calling station for moving the traveling contact device of the first-selector, and means operated over said trunk lines for making the final connection between subscribers' lines.

66. In an automatic telephone system, the combination, with the subscribers' lines divided in groups and in sub-groups, and, for each line group local circuits equal in number to the number of the sub-groups; for each line group a plurality of preselectors, each comprising subscribers' line contacts arranged in series corresponding to the sub-groups, a traveling contact device and means for moving the traveling contact device to the series of contacts and along these, a calling relay in each subscriber's line arranged to set in action an idle preselector upon a call and to alter the condition of the local circuit of the sub-group to which its line belongs; for each line group a common auxiliary switch coupled with an idle preselector ready for a call and working synchronously with the preselector and arranged to stop the traveling contact device of the preselector at the series of contacts of the calling subscriber's sub-group and for causing said traveling contact device to come over the contacts of the calling subscriber's line.

67. In an automatic telephone system, the combination, with the subscribers' lines divided in groups, a plurality of preselectors and selectors arranged in pairs, and a plurality of connectors for each line group, each preselector, selector and connector comprising line contacts, a traveling contact device and means for moving its traveling contact device into engagement with its line contacts, the traveling contact device of each preselector being in electric communication with the traveling contact of its corresponding selector, an auxiliary switch common to a plurality of preselectors, coupled for a call with one of said preselectors, and working simultaneously with the same, the subscribers' lines of the group being connected in multiple as incoming lines to the line contacts of the preselectors and as outgoing lines to the line contacts of the connectors, a system of trunk lines divided in sets and each connected in multiple to the respective line contacts of the selectors and to the traveling contact device of a corresponding connector, means for the automatic working of the preselectors to set the traveling contact device of an idle preselector on a calling line, and means at the subscribers' stations to start an idle preselector and for actuating and controlling its corresponding selector and a connector of the desired subscriber's line group.

68. In an automatic telephone system, the combination, with the subscribers' lines divided in groups, a plurality of preselectors and first-selectors arranged in pairs, a plurality of connectors, and a plurality of intermediate selectors for each line group, each preselector, first-selector, intermediate selector and connector comprising line contacts, a traveling contact device and means for moving its traveling contact device in engagement with its line contacts, the traveling contact device of each preselector being in electric communication with the traveling contact device of its corresponding first-selector, an auxiliary switch common to a plurality of preselectors, coupled for a call with one of said preselectors, and working simultaneously with the same, systems of trunk lines, one system for each plurality of selectors, the trunk lines of each system being divided in sets and each trunk line connected in multiple to the respective contacts of its corresponding selectors and to the traveling contact device of a succeeding selector or connector, the subscribers' lines of the group being connected in multiple as incoming lines to the line contacts of the preselectors and as outgoing lines to the line contacts of the connectors, means for the automatic working of the preselectors to set the traveling contact of an idle preselector on a calling line, and means at the subscribers' stations to start an idle preselector and for actuating and controlling its first-selector, the selected intermediate selectors, and a connector of the desired subscriber's line group.

69. In an automatic telephone system, the combination, with the subscribers' lines divided in groups, of a plurality of double switches, each consisting of a preselector and a selector, and a plurality of single switches, each consisting of a connector, for each line group, each preselector, selector and connector comprising line contacts, a traveling contact device and means for moving its traveling contact device into engagement with its line contacts, the traveling contact device of each preselector being in electric communication with the traveling contact of its corresponding selector, an auxiliary switch common to a plurality of preselectors, coupled for a call with one of said preselectors, and working simultaneously with the same, the subscribers' lines of the groups connected in multiple as incoming lines to the line contacts of the preselectors, and as outgoing lines to the line contacts of the connectors, and a system of trunk lines divided in sets and each connected in multiple to the respective line contacts of the selectors and to the traveling contact device of a corresponding connector, the double switches being arranged to make connections from a calling subscriber's line to an unoccupied trunk line of the desired subscriber's line group, each of the single switches being arranged to make connections from its incoming trunk line to a desired subscriber's line.

70. In an automatic telephone system, the combination, with the subscribers' lines divided in groups, a plurality of double switches, each double switch consisting of 5 a preselector and a first-selector, and a plurality of single switches, part consisting of connectors and part of intermediate selectors, each preselector, first-selector, intermediate selector, and connector comprising 10 line contacts, a traveling contact device and means for moving its traveling contact device in engagement with its line contacts, the traveling contact device of each preselector being in electric communication with 15 the traveling contact device of its corresponding first-selector, an auxiliary switch common to a plurality of preselectors, coupled for a call with one of said preselectors, and working simultaneously with the same, 20 systems of trunk lines, one system for each plurality of selectors, the trunk lines of each system being divided in sets and each trunk line connected in multiple to the respective contacts of its corresponding selectors and to 25 the traveling contact device of a succeeding selector or connector, the subscribers' lines of the group being connected in multiple as incoming lines to the line contacts of the preselectors and as outgoing lines to the 30 line contacts of the connectors, the double switches being arranged to make connection from a calling subscriber's line to an unoccupied first trunk line of the desired set, the single switches being arranged to continue 35 the connection from trunk line to trunk line and finally to the desired subscriber's line.
71. In an automatic telephone system, the combination, with the subscribers' lines divided in groups, of a plurality of preselectors and first-selectors for each line group, each comprising line contacts, a traveling contact device arranged to engage its line contacts, and means for moving the traveling contact device, the traveling contact device of each preselector being in electrical communication with that of one of the first-selectors, the contacts of the preselectors being connected to the corresponding subscribers' lines, trunk lines connected in multiple to the first-selectors, an auxiliary switch common to a plurality of preselectors, coupled for a call with one of said preselectors and arranged to drive its traveling 45 contact device to the contacts of the calling subscriber's line, switching apparatus controlled by the preselectors and arranged to bring the next idle preselector into the sphere of control of the said auxiliary switch, means actuated at the calling station for moving the traveling contact device of the first-selector, and means operated over said trunk lines for making the final connection between subscribers' lines.
72. In a telephone system, a calling device, a plurality of magnets, a series circuit passing through contacts controlled by said magnets, and means whereby any two of said magnets may be operated to thereby control the impulses sent out by said calling 70 device, substantially as described.
73. In a telephone system subscribers' lines, finder switches less in number than said subscribers' lines, said finder switches being normally at rest, means for starting 75 and operating an idle one of said finder switches to cause it to connect with the calling subscriber's line responsive to said calling subscriber removing his receiver.
74. In a telephone system, means for establishing a connection between a calling and a called line, said means comprising a finder switch, a selector switch and a connector switch, all of said switches having motion in two intersecting planes.
75. An automatic telephone system comprising a calling subscriber's line, means having two kinds of motion under the control of the subscriber for calling any other subscriber, and automatic impulse-transmitting means at the central station, but under the control of the calling subscriber, for automatically calling one or more digits in the number of his own substation including the final digit in such number preliminary 90 to or just before calling the number of some other subscriber.
76. In a telephone system subscribers' lines, finder switches less in number than said subscribers' lines, means for operating 100 an idle one of said finder switches to cause it to connect with the calling subscriber's line when said calling subscriber removes his receiver, and a trunk release circuit for said finder switch.
77. In a telephone system subscribers' lines, relays individual to said subscribers' lines, trunk lines less in number than said subscribers' lines, finder switches for said trunk lines, means for energizing one of said 105 relays over a calling subscriber's line, means responsive to the energization of such relay and independent of any numerical operation at the calling station to cause an idle finder switch to connect with the subscriber's line, 110 and a trunk release circuit for said finder switch.
78. In a telephone exchange system, a plurality of line circuits, link circuits for interconnecting them, and primary selector switches for said links, each containing groups of line terminals, together with means responsive to current in a calling line adapted to direct a primary selector switch first to the group of contacts in which said line is represented and then to the individual line contact in the group.
79. In a telephone exchange system, a plurality of circuits to be selected, a selector switch containing terminals for said circuits 125

fixed in a prearranged order, and testing means adapted to drive the switch step by step in response to current change in a given circuit, to select said circuit in a number of steps less than the number represented by the whole number of the given line terminals in their order of arrangement.

80. In a telephone system, a line, a relay for said line, an automatic progressively movable switch for finding said line, means for automatically operating said switch responsive to the operation of said line relay, and a cut-off relay for rendering said line relay inoperative when the line is found.
- 15 81. In a telephone system, a line, a relay for said line, an automatic progressively movable switch for finding said line, means for automatically operating said switch responsive to the operation of said line relay, and a cut-off relay for rendering said line relay inoperative when the line is found, said line and cut-off relays being individual to the line.

82. In a telephone system, a line, a switch for finding said line, a relay individual to said line for controlling said switch, a cut-off relay for controlling said first relay, a telephone for said line, said telephone being provided with impulse-sending means, means whereby a non-numerical impulse operation at the telephone will cause the switch to establish connection with the line and energize the cut-off relay to render the line relay inoperative, a numerical switch for extending connection from the line after the finder switch stops on the line, said numerical switch responsive to numerical operations from the telephone.

83. A telephone exchange system comprising a plurality of telephone lines, a plurality of link-circuits, automatic switch mechanism associated with each link-circuit for connecting its link-circuit with a desired line, a master switch having a fixed contact corresponding to each link-circuit, a co-operating movable contact, and means for causing said movable contact to move out of engagement with the fixed contact of any link-circuit upon its selection and connection to a telephone and to move into engagement with the fixed contact of an idle link-circuit.

84. In a controlling apparatus, a line, an impulse device associated therewith, devices for actuating said impulse device, means actuated upon the operation of any one of said actuating devices for causing said impulse device to make a certain definite number of electrical contacts, and means governed by the operated actuating device for determining the number of said electrical contacts which will be effective to alter the electrical condition of said line.

85. In a controlling apparatus, a series of actuating devices, a series of normally elec-

trically connected impulse contacts, a wiper, means operated upon the actuation of one of said devices for causing said wiper to traverse the contacts of said series, and means also operated by such actuation for interrupting the electrical connection to certain of said contacts.

70 86. In a controlling apparatus, a series of actuating devices, a series of normally electrically connected impulse contacts corresponding thereto, a conducting strip, a wiper, means operated upon the actuation of any one of said devices for causing said wiper to successively connect said contacts to said conducting strip, and means also operated by such actuation for interrupting the electrical connection between certain contacts of said series.

75 87. A telephone system including telephone lines, selective switches to select said lines, a traveling switch, a contact for each said selective switch associated therewith, electrically controlled adjusting mechanism for causing said traveling switch to normally rest engaging the contact of an idle selective switch, and connections whereby any line may influence said traveling switch to start said idle switch.

80 88. A telephone system including telephonic circuits having multiple contacts, a plurality of selectors for selecting said contacts, a distributor switch for starting said selectors, automatically controlled mechanism for adjusting said switch so that it normally rests maintaining established a 90 normal connection therefrom to an idle selector, and means controllable over any of said telephone circuits for causing said distributor switch to change the electrical condition of said connection to start the idle selector to select the circuit.

85 89. A telephone exchange system comprising a plurality of electrically controlled devices, a switch for controlling said devices, operating means for said switch at rest only 100 when a path for current extends through the switch contacts to an idle one of said devices, and means controlled by said switch for causing a current flow over said path.

90. A telephone system comprising a plurality of subscribers' lines, electrically controlled selective devices for connecting said lines as calling lines, a master switch for said switches, operating means for said switch at rest only when a path of current extends through said switch to an idle one of said selective devices, and means responsive to the initiation of a call over one of said lines for operating said switch to cause a current flow over said path.

115 91. A telephone system including telephone lines, multiple terminals for said lines at the exchange, selectors for selecting terminals of said lines responsive to calls initiated thereover, line relays one for each 120 125 130

line, a distributor switch for starting said selectors, branch connections from said distributor switch to said line relays, whereby any line relay when operated may influence 5 said distributor, a pair of contacts for each selector at said switch, a pair of movable contact makers for said switch adapted to engage said pairs of contacts, magnets for said selectors for operation to cause travel 10 of their respective selectors, a circuit of said distributor switch controlled by the line relays of said lines for energizing the magnet of an idle selector, said circuit including one of said contact makers, the contact of 15 an idle selector engaged thereby and the magnet of such selector, an electromagnet of said distributor switch controlling travel thereof, and a circuit for said magnet sensitive to the idle or busy conditions of said 20 selectors, said circuit including the other contact maker of said switch and the contact of the selector engaged thereby.

92. A telephone system including telephone lines, multiple terminals for said lines 25 at the exchange, selectors for selecting terminals of said lines responsive to calls initiated thereover, line relays one for each line, a distributor switch for starting said selectors, branch connections from said distributor switch to said line relays, whereby any line relay when operated may influence said distributor, a pair of contacts for each selector at said switch, a pair of movable contact makers for said switch adapted to engage 30 said pairs of contacts, magnets for said selectors for operation to cause travel of their respective selectors, a circuit of said distributor switch controlled by the line relays of said lines for energizing the magnet 35 of an idle selector, said circuit including one of said contact-makers, the contact of an idle selector engaged thereby and the magnet of such selector, an electromagnet of said distributor switch controlling travel thereof, a circuit for said magnet sensitive to the idle 40 or busy conditions of said selectors, said circuit including the other contact makers of said switch and the contact of the selector engaged thereby, and an off normal contact 45 of the selector also included in said circuit.

93. A telephone system including telephone lines arranged in groups, said groups being divided into sub-groups, multiple terminals of said lines similarly arranged and divided, line relays, one for each line, a sub-group relay common to and operable by the line relays of a sub-group, a common starting conductor with branches to the sub-group relays of a line group whereby any 55 sub-group relays of a line group may control the electrical condition of said conductor, selective switches for selecting the multiple terminals of calling lines, and means for interchangeably operatively connecting idle

ones of said switches with said starting conductor. 65

94. A telephone exchange system comprising a plurality of subscribers' telephone lines divided into groups, a plurality of interconnecting link-circuits, a plurality of electrically controlled switches for completing connections between any calling lines and any called lines, said switches including line selectors assigned by groups to groups of lines, and the total number of said switches being 70 less than the total number of said telephone lines no matter how many of the latter there may be in the exchange, and means for establishing as many simultaneously existing conversational circuits between pairs of lines all 75 in the same group as there are line selectors for the group.

95. A telephone exchange system comprising a plurality of subscribers' telephone lines, a plurality of interconnecting link-circuits, a plurality of electrically controlled 80 selectors for completing connections between any calling line and any called line, the total number of said switches being less than the total number of said telephone lines 85 no matter how many of the latter there may be in the exchange, switch contacts for each of said selectors adapted to be traversed by the voice currents when the selectors are included in connections, and means whereby the switching of a calling line to connection 90 with a called line will operate only those selectors whose contacts are included in the finally completed talking circuit.

96. A telephone system including 100 telephone lines, link-circuits having electrically controlled selective switches at each end, the switches at the answering ends of said link-circuits serving to select calling lines, line relays for said lines, a circuit for starting 105 the switches at the answering ends of the link-circuits, said circuit having normal starting connections, means for rendering said circuit effective when any line relay is operated, and means rendering said circuit 110 ineffective with respect to subsequently established starting connections until another line relay is operated.

97. A telephone system including telephone lines, line selectors for selecting calling lines provided in number determined by the expected co-existing calls from said lines, connectors for connecting to the called line provided in number based upon the expected 115 percentage of co-existing calls, one or more 120 classes of intermediate group selecting switches, the switches of each class being provided in number similarly determined, and the classes being provided in number dependent upon the number of said telephone 125 lines, electromagnetic switching mechanism to adjust one switch of each class to establish a complete talking circuit between a

calling line and a called line, and means for operating said line selectors to connect each with a different line.

98. A telephone system including telephone lines, link-circuits at the exchange having electrically operated selective switches at both ends, the switches at the answering ends of said link-circuits serving when started to connect link-circuits with calling lines, a starting conductor for initiating travel of predetermined numbers of idle ones of said last-mentioned selective switches, and line relays for said lines, and branch connections from said conductor to said relays whereby any line may control said conductor to start a switch.

99. A telephone system including telephone lines, link-circuits at the exchange having electrically operated selective switches at both ends, the switches at the answering ends of said link-circuits serving when started to connect link-circuits with calling lines, a starting conductor for initiating travel of one idle switch only of said last-mentioned selective switches, line relays for said lines and branch connections from said conductor to said relays whereby any line may control said conductor to start a switch, and means for connecting the selective switches at the calling ends of said link-circuits with definite conductors.

100. A telephone system including telephone lines, link-circuits at the exchange having electrically operated selective switches at both ends, the switches at the answering ends of said link-circuits serving when started to connect link-circuits with calling lines, a starting conductor for initiating travel of an idle one of said last-mentioned selective switches, and operatively associated with all said lines at one time, an automatic switch at the end of said starting conductor, terminals of said selective switches at said automatic switch, and test means enabling said automatic switches to select a terminal of an idle selective switch.

101. A telephone system including telephone lines, link-circuits at the exchange having electrically operated selective switches at both ends, the switches at the answering ends of said link-circuits serving when started to connect link-circuits with calling lines, a starting conductor for initiating travel of an idle one of said last-mentioned selective switches, line relays for said lines and a branch connection from said conductor to said relays whereby any line may control said conductor to start a switch, an automatic switch at the end of said starting conductor, terminals of said selective switches at said automatic switch and test means enabling said automatic switch to select a terminal of an idle selective switch.

102. A telephone system including tele-

phone lines, link-circuits at the exchange having electrically operated selective switches at both ends, the switches at the answering ends of said link-circuits serving to connect them with calling lines, a starting conductor for initiating travel of an idle one of said last-mentioned selective switches, means for connecting the selective switches at the calling ends of said link-circuits with definite line conductors, line relays for said lines and a branch connection from said conductor to said relay whereby any line may control said conductor to start a switch, an automatic switch at the end of said starting conductor, terminals of said selective switches at said automatic switch, and test means enabling said automatic switch to select a terminal of an idle selective switch.

103. A telephone system including a group of telephone lines, terminals therefor at the exchange grouped together and arranged in sub-groups, link-circuits at the exchange and selective switches therefor to connect idle link-circuits with calling lines, a common starting circuit, for initiating travel of an idle selective switch, operatively associated with said lines at one time, normally quiescent switching means at the exchange and at the substations of said lines effective on initiations of class to actuate said starting circuit, and electromagnetic switching mechanism at the exchange automatically responsive to said means to control travel of a started switch to select the sub-group and then the terminals of the calling line.

104. A telephone system including a group of telephone lines, terminals therefor at the exchange grouped together and arranged in sub-groups, link-circuits at the exchange and selective switches therefor to connect idle link circuits with calling lines, a common starting circuit, for initiating travel of an idle selective switch, operatively associated with said lines at one time, normally quiescent switching means at the exchange and at the substations of said lines effective on initiations of calls to actuate said starting circuit, electromagnetic switching mechanism at the exchange automatically responsive to said means to control travel of a started switch to select the sub-group and then the terminals of the calling line, and an automatic switch at the end of said starting circuit serving to determine the idle switch to be started.

105. A telephone system including telephone lines, selective switches to select said lines as calling lines, trunk selecting switches paired with said first-mentioned switches serving to extend the circuits of selected calling lines, master-switch mechanism normally common to said lines for selecting an idle selective switch, means for initiating travel of

said mechanism, and off-normal switches for said selective switches serving when shifted to continue travel of said mechanism to select a selective switch having its off-normal 5 switch unshifted or at normal.

106. A telephone system including telephone lines, selective switches to select said lines as calling lines, trunk selecting switches paired with said first-mentioned switches 10 serving to extend the circuits of selected calling lines, master-switch mechanism normally common to said lines for selecting an idle selective switch, means for initiating travel of said mechanism, and off-normal 15 switches for said selective switches controlling the extent of travel of said mechanism.
107. A telephone system including a group of telephone lines, a line relay for each of said lines, a group relay common to said 20 lines adapted to be operated responsive to any of said line relays, a plurality of automatic switches adapted to connect with said lines, a switch contact of said group relay for interchangeable association with said 25 switches, whereby the operation of said group relay automatically starts an idle switch, and selective switches connected to said automatic switches for operation responsive to currents controlled at the sub- 30 stations.

108. A telephone system including a group of telephone lines, a line relay for each of said lines, a group relay common to said 35 lines adapted to be operated responsive to any of said line relays, a plurality of automatic switches adapted to connect with said lines, a switch contact of said group relay for interchangeable association with said 40 switches, whereby the operation of said group relay automatically starts an idle switch, selective switches connected to said automatic switches for operation responsive to currents controlled at the substations, and link-circuits connected with said automatic 45 switches for use in extending the circuits of calling lines to called lines.

109. A telephone exchange system comprising subscribers' telephone lines divided into groups, interconnecting link-circuits, 50 line selectors assigned by groups to the groups of lines, electrically directly controlled switches for co-operating with said line selectors to unite calling and called lines for conversation through said link-circuits, manual impulse transmitting means at the 55 substations for directly controlling said latter switches, and means for establishing as many simultaneously existing conversational circuits between pairs of lines all in 60 the same group as there are line selectors for the group.

110. A telephone exchange system comprising subscribers' telephone lines, interconnecting link-circuits, line selectors, and electrically directly controlled switches for 65

co-operating with said line selectors to unite said lines into conversational circuits, manual impulse transmitting means at the substations for controlling said directly controlled switches, and means whereby the 70 act of establishing such a conversational circuit will operate only those switches whose contacts are included in the finally completed talking circuit.

111. A telephone exchange system comprising calling lines, line selectors operative to connect each with a different calling line, called lines, connectors for establishing connection with the called lines, interconnecting link circuits, and intermediate switches of 75 different classes for uniting said link-circuits and lines into conversational circuits, each class of intermediate switches having a total 80 number of switches not exceeding the total number of line selectors for exchanges of 85 any number of lines.

112. A telephone exchange system comprising calling lines, line selectors operative to connect each with a different calling line, called lines, connectors for establishing connection with the called lines, interconnecting link-circuits, and intermediate switches of 90 different classes for uniting said link-circuits and lines into conversational circuits, each 95 class of intermediate switches having a total number of switches not exceeding the total number of connectors for exchanges of any 100 number of lines.

113. A telephone system including telephone lines, line selectors for selecting calling lines, connectors for connecting to called lines, one or more classes of intermediate group selecting switches, the classes being provided in number proportioned to the 105 number of said telephone lines, electromagnetic switching mechanism to adjust one switch of each class to establish a complete talking circuit between a calling line and a called line, and means for operating said line selectors to connect each with a different 110 line.

114. A telephone system comprising telephone lines and associated electric switch mechanism having waiting contacts arranged in groups, a co-operating contact movable in a primary direction to the different groups and in a secondary direction to the waiting contacts in the groups, means for starting said movable contact in a primary direction, and automatic means for causing its further primary movement to a definite group and then its secondary movement to a definite contact in said group.

115. A telephone system comprising telephone conductors and associated electric switch mechanism having waiting contacts forming terminals of said conductors and arranged in groups, a co-operating contact movable primarily to the different groups and secondarily to the waiting contacts in 125 130

- the groups, means for starting said movable contact, and automatic means for continuing its movement to a definite group, and then to a definite contact in the group.
- 5 116. A telephone system including a group of telephone lines, a line relay for each of said lines at the exchange, a group relay common to the lines of the group, a further division of said groups into sub-groups, a 10 sub-group relay common to the lines of a sub-group, means for operating the line relay of a line initially by currents controlled at the substation, and energizing circuits for said group and sub-group relays controlled 15 by said line relay.
117. The combination with a plurality of telephone lines arranged in groups, a group relay associated with each group and operated by any of the lines of the corresponding 20 group, a group selecting mechanism selectively controlled by said relays, a relay common to said groups, initial energizing circuits for said group relays controlled by said common relay, and an energizing circuit for said common relay controlled in 25 the operation of any of said group relays.
118. The combination with a plurality of telephone lines arranged in groups, of a group relay for each group operated by 30 any line of the corresponding group in calling, group selecting means under the control of said group relays, an energizing circuit having a branch for each of said group relays, and a relay in the common portion 35 of said energizing circuit for preventing the operation of the other group relays when any one of said group relays is operated.
119. In a telephone exchange system, the combination of a telephone line, a line relay individual to the said telephone line and 40 normally connected in bridge thereof, a cut-off relay for opening said bridge, a circuit for energizing said cut-off relay, automatic means for closing said circuit when the line calls, controlled by the calling subscriber, and another circuit for energizing the cut-off relay when the line is called.
120. In a telephone system, a subscriber's line, an automatic switch associated with 45 said line, means including said switch for extending said line when calling, an automatic subscriber controlled connector switch having direct access to said line for connecting with said line as a called line, a line 55 relay individual to said line and normally connected in bridge of the same, a cut-off relay for opening said line relay bridge, and circuits for energizing said cut-off relay whenever said line is calling or is being 60 called.
121. In a telephone system, a subscriber's line, an automatic switch associated with said line, means including said switch for extending said line when calling, means for 65 connecting with said line as a called line, a line, relay for said switch individual to said line and normally connected in bridge of the same, a cut-off relay for opening said bridge, and circuits for maintaining said cut-off relay energized throughout the connection 70 when said line is engaged either as a calling or as a called line.
122. In a telephone system, an automatic switch, a trunk line extending to said switch and including talking conductors permanently connected to the switch wipers, operating conductors leading to the operating magnets of said switch, and an impulse machine at the exchange common to said switch and other similar switches for transmitting 75 impulses over said operating conductors.
123. In a telephone system, a group of link circuits for use in connecting calling and called lines, automatic switches associated with said link circuits, a common normally at rest sender at the exchange for transmitting impulses to said switches, and means associated with said sender and controlled from a calling subscriber's station for starting the sending and for determining the 80 number of impulses to be transmitted.
124. In a telephone system, a group of trunk lines for use in connecting calling and called lines, a branch for each of said trunk lines, an impulse transmitting device at the exchange common to said branches, means for associating said device with any branch and for operating the device to send a plurality of series of impulses over the branch 85 with which it is associated, subscriber controlled means associated with said device for determining the number of impulses in each series, and impulse controlled automatic switching mechanism associated with said trunk lines.
125. In a telephone system, a group of lines, a finder switch, a set of tens relays and a set of units relays, means controlled over a calling line for energizing the corresponding relays, and a device controlled by the energized relays for sending the proper series of impulses to said finder to set the 90 same on the calling line.
126. In a signaling system, an impulse transmitter including a series of contacts, a contact maker adapted to be rotated over said contacts, means for transmitting an impulse when said contact maker comes in contact with each contact, and an impulse spacer for preventing impulses being transmitted when said contact maker comes in contact with certain of said contacts.
127. In a signaling system, an impulse transmitter including a series of normally closed contacts, automatic means for opening certain of said contacts, and means for transmitting a plurality of series of impulses, the number of impulses in each series being dependent upon the particular contacts which are opened.

128. In a signaling system, means for transmitting a plurality of series of impulses, said means including a series of local circuits normally closed at one point and normally opened at a second point, an impulse spacer for opening certain of said normally closed points, and a contact maker adapted to successively close said normally open points.
- 10 129. In a telephone system, a subscriber's line, an automatic switch associated with said line, a second subscriber's line, means for establishing connection from said first to

said second subscriber's line, or from said second line to said first line, a line relay individual to said first subscriber's line and bridged across the same for controlling said automatic switch, and a cut-off relay for disconnecting said line relay from across the line when said first line is calling, said cut-off relay also for disconnecting said line relay from across the line when said first line is called.

Signed by me at Chicago, Cook County, Illinois, this 7th day of March, 1905.

JOHN ERICKSON.
